UNITED STATES PATENT OFFICE

JOHN A. BOYCE, OF SPRINGFIELD, ILLINOIS.

APPARATUS FOR PRINTING AND FOLDING PAPERS.

1,149,620.

Specification of Letters Patent. Patented Aug. 10, 1915.

Original application filed October 1, 1906. Serial No. 336,856. Divided and this application filed September 3, 1910. Serial No. 580,489.

To all whom it may concern:

Be it known that I, JOHN A. BOYCE, residing at Springfield, in the county of Sangamon and State of Illinois, and a subject 5 of the King of Great Britain, as evidenced by the certificate of the clerk of the county court of Sangamon county, Illinois, now on file in the Patent Office, have invented a new and useful Apparatus for Printing and 10 Folding Papers, of which the following is such a full, clear, and exact description as will enable others skilled in the art to make and use my said invention.

This application is a divisional part of 15 my pending application, S. N. 336,856, apparatus for printing and folding papers, filed Oct. 1, 1906, and on which U. S. Patent No. 974,231 was granted to me November 1, 1910.

20 The annexed drawings to which reference is hereby made, are in the nature of diagrams.

25 Rotative parts such as plate cylinders, impression cylinders, cutter and carrier cylinders, web propelling rollers, folder rollers, etc., are actuated, at full speed, or at half speed, as set forth, by suitable gears well known in the art which will be herein-after described.

30 It is to be understood that where mechanisms, or parts of mechanisms, are not shown, but are described, that such mechanisms, or parts of mechanisms, may be of any usual or approved construction suitable for the 35 purpose set forth.

The invention contemplates a multiple deck apparatus employing plate cylinders in circumference equal to the width of two 40 pages plus margins and in length equal to the length of a plurality of pages plus margins and equipped with plates having columns length-wise of the plate cylinders and employing a plate area of four pages available 45 for main pages or optionally available for supplement pages; if supplements are used; and invariably utilizing the entire plate area of the printing mechanisms when producing book-form papers with, or without, supplements; or when producing papers 50 in sections, with, or without, supplements; or when producing papers in sections, one section with supplement and the other section without supplement.

The purposes of the invention are to pro- 55 vide in conjunction with printing mecha-

nisms adapted to print on continuously moving webs in width equal to the length of two pages plus margins, the matter of pages in pairs of rows, the pages of one row of a pair being end-to-end with respect to 60 the pages of the other row of the same pair and separated therefrom by the usual margin, and the columns of the pages being crosswise of the web; means for associating in single alinement in one group all the 65 webs, or web-members, comprising the matter of one row of pages and to associate in single alinement in another group all the webs, or web-members comprising the matter of the other row of pages; to provide a 70 supplement cutter positioned to operate on a web or web-member of either row; to provide means for propelling the supplement web, or web-member, to the supplement cutter and carrier and between face-to-face 75 main webs or web-members which were initially edge-to-edge with respect to each other; to provide main carriers adapted to carry the respective face-to-face groups of main webs, or web-members; to provide 80 means for associating both face-to-face groups of main webs, or web-members, on one main carrier; to provide means for inserting the supplement sheets with the groups of webs, or web-members, running 85 on the main carriers respectively and likewise adapted to insert supplement sheets between associated groups of webs or web-members running on one main carrier; to provide cutter mechanisms, first and second 90 folder mechanisms and delivery devices co-operating with one carrier, or with both carriers; and to provide pasters adapted to apply paste on the face of that web or web-member of each group which runs next to 95 the supplement web or web-member.

With these general purposes in view more specific purposes of the invention are to provide printing mechanisms having plate cylinders in circumference equal to the width 100 of two pages plus margins and in width equal to the combined lengths of a plurality of pages plus margins and adapted to perform continuously moving webs; to provide a slitter, or slitters, adapted to slit the perfected webs along the margin between the adjacent ends of the pages to divide the web into web-members in width equal to the length of one page plus margins; to provide turners adapted to effect a single quar- 110

ter turn of the web-members to associate in one group all the right hand members of a plurality of webs and to associate in another group all of the companion or left hand members of the same webs, the groups of quarter-turned web-members being face-to-face with respect to each other and comprising web-members initially running edge-to-edge with respect to each other; to provide means for introducing and cutting a supplement web or web-member between the face-to-face groups of main web-members; and to provide means for associating the supplement sheets with the main webs or web-members of one group, or optionally associating them alternately, with the main webs, or web-members, of the respective groups.

Figures 1, 2 and 3 are respectively a top plan, an end elevation, and a side elevation of the apparatus, the gears being omitted; Fig. 4 is an isometric view illustrating the run of the web-members and the supplement sheets; Fig. 5 is an enlarged detail of the supplement cutter and carrier mechanism; Figs. 6, 7, 8 and 9 are enlarged views illustrating the construction and modes of operation of the switches; Fig. 10 is an enlarged view, partially in section, illustrating details of one of the main cutter cylinders; Fig. 11 is a transverse section on the line 56, 56 of Fig. 10; Figs. 12, 13 and 14 are respectively a front elevation, a fragmentary top plan, and a fragmentary side elevation showing conventionally the trains of gears actuating the different mechanisms. Fig. 15 is a diagrammatic elevation, on an enlarged scale, of one of the supplement cutting cylinders, showing one cutting wood in position on the cylinder and the pin holes in the cutting wood; Fig. 16 is an enlarged partial vertical section on the line S. S. of Fig. 15; and Fig. 17 is an enlarged partial vertical section on the line T. T. of Fig. 15. Similar reference characters designate like parts in the several views.

The apparatus comprises printing mechanisms, slitters, turners, supplement cutter and carrier mechanisms, main carriers, main cutters, first and second folders, and delivery devices; in coöperative relation substantially as hereinafter set forth.

The main frame 1 supports revoluble plate cylinders 2 and revoluble impression cylinders 3 coöoperating with the plate cylinders. I have shown three sets of printing mechanisms adapted to perfect three continuously moving webs, A, B, and C, but a greater number of sets of printing mechanisms may be used without departure from my invention.

I have shown printing couples in length equal to the length of two pages plus margins, but printing couples in length equal to the length of three or more pages plus

margins may be used without departure from my invention. Each plate cylinder 2 is in length equal to the length of two pages plus margins and in circumference equal to the width of two pages plus margins and is 70 equipped with plates having columns lengthwise of the plate cylinder. Each revolution of the printing couples perfects four pages; the pages on one member of any given web being end-to-end with respect to 75 the pages on the companion member of the same web.

If a supplement web in width equal to the length of one page plus margins is used, the pages of the supplement web will be end-to-end with respect to the pages of a main web, or web-member, running coincidentally, with one edge of the main web, or web-member, in the same vertical plane with one edge of the supplement web, or web-member. 85

Preferably one deck of the printing machine has plate cylinders equipped with main plates occupying one-half the length of each plate cylinder and supplement plates occupying the other half of the length of 90 the same plate cylinder; but the supplement pages may be printed by printing couples occupying half the length of one deck and the main pages may be printed by printing couples occupying the entire length of another deck, or other decks. I have shown the supplement web running on the top deck of the printing machine but any other deck of the printing machine may be used to print the supplement web or to print a composite web comprising the matter of main pages on one web-member and the matter of supplement pages on the other member of the same web. A rotating roller 72 transverse to the main frame carries the associated webs A, B and C. Pulling wheels 73 coöperate with the roller to propel the associated webs. A slitter 24 serves to slit centrally the associated webs.

Diverging angle bars P mounted on the 110 main frame serve to effect a quarter-turn of the web-members running around the angle bars so that the quarter-turned members will constitute two face-to-face groups R, and L, each group comprising a plurality of web-members, and each web-member being in width equal to the length of one page plus margins.

The main web-members comprise the matter of main pages only and the supplement 120 web or web-member comprise the matter of supplement pages only. The group R usually comprises all the right hand main web-members printed by the right-hand half of the printing couples, and the group L usually comprises all the left-hand main web-members printed by the left-hand half of the printing couples; but either group may comprise web-members printed on both halves of the printing couples, that is to 125 130

say; a web or web-member, or a plurality of webs or web-members, printed by the right hand printing couples, may run above and across the cylinder 7 as indicated by the arrow V in Fig. 4, and may be associated with the webs, or web-members, running on the cylinders 7, or conversely a left hand web or web-member, or a plurality of webs or web-members, may run above and across the cylinder 7 and may be associated with the webs or web-members running on the cylinder 7. The supplement web-member may be printed by either half of the printing couples and may be associated with main web-members of group R or group L according as the supplement web-member is printed by a right-hand or a left-hand printing couple.

The supplement cutter and carrier mechanism is located between and in range with the groups R and L of web-members running on the rollers Z and Z' and comprises a cutter cylinder 4, a carrier cylinder 5, rollers 75, tapes 75, running on the rollers 75^a; rollers 75^b and tapes 75' running on the rollers 75'. The supplement cutter and carrier cylinders 4 and 5, are adapted to cut the supplement web into one-leaf sheets and may be operated at half speed to supply supplement sheets to be inserted with main sheets running on one main carrier, or may be operated at full speed to supply supplement sheets alternately to be inserted with main sheets running on both main carriers. The cylinders 4 and 5 are between and in range with the web-forwarding rollers Z and Z' and in position to operate on a web or web-member forwarded by the roller Z and likewise in position to operate on a web or web-member forwarded by the roller Z'.

The means for operating the supplement cutter and carrier cylinders at full speed, or half speed, may be of any usual or approved construction. I prefer to use gears substantially as shown in my said application #326,856, to operate the supplement cutter and carrier at full speed, or at half speed.

I will now describe the trains of gears preferably used to actuate the different mechanisms. The mechanisms are driven by a suitably placed motor 30 of any approved construction. A gear wheel 31 rigid on the motor shaft meshes with a gear 35 rigid on the rotative transverse shaft 40. Intermediate gears 36 and 37 connect the gear 35 with the gear 38 on the shaft of one plate cylinder 2. The gear 37 is adapted to slide outwardly on a stationary stud 37', to put the printing mechanisms out of commission. Intermeshing gears 38 on the shafts of the plate and impression cylinders, and intermediate gears 39 drive the plate cylinders and impression cylinders at full

speed. The uppermost intermediate gear 39 is mounted to rotate and slide outwardly on the stud 39^a to the position indicated by dotted lines in Fig. 12 to disengage the gear 39^b from the gears 38, and place the cylinders of the top deck out of commission. The plate and impression cylinders of one deck, preferably the upper deck, may be rotated at half-speed by intermeshing gears 38^c, 39^b and 38^a. The intermediate gear 39^b is mounted to rotate and slide on a fixed stud 39^e and may be slid outward on the stud to the position indicated by dotted lines in Fig. 12 to disengage the gear 39^b from the gears 38^c and 38^a. Bevel cog gears 60 60' 70 75 80 are secured on the rotative vertical shaft 42 and bevel gears 43 and 44 are secured on the rotative vertical shaft 42'. The gears 43 and 43' mesh with and are driven by the gears 41 and 41' respectively. Bevel gears 45^b and 45^{b'} (Fig. 13) are fixed on horizontal rotative shafts 45^a and 45^{a'} respectively and are driven by the gears 44 and 44' 85 respectively. A spur gear 45 is fixed on the shaft 45^a and a broad-faced gear 45' is fixed on the shaft 45^{a'}. Gears 47 and 47' are fixed on the shafts of the horizontal web-forwarding rollers Z and Z' and are driven by the gears 45 and 45' respectively. Gears 48 and 48' are fixed on the shafts of the main cutter cylinders respectively and mesh with and drive gears 50 and 50' fixed on the shafts of the main carrier cylinders 7 and 7' respectively. A gear 49 is mounted to slide on the rotative paster shaft 49^a and intermeshes with the gears 45 and 48, and may be slid outward on the shaft to put the cylinders 6 and 7 out of commission. A gear 49' is mounted to slide on the rotative paster shaft 49^{a'} and intermeshes with the gears 45' and 48' and may be slid outward on the shaft to put the cylinders 6' and 7' out of commission. 100 105 110

Gears 51 and 51' are connected with the folder rollers 8 and 8' and mesh with and are driven by the gears 50 and 50' respectively. Intermeshing gears (not shown) at the ends of the rollers 8 and 8^a remote from the gear 51, cause the rollers to rotate in unison to propel sheets downwardly between the rollers, and similar intermeshing gears connected in like manner with the rollers 8' and 8^{a'} cause said rollers to rotate in unison to propel sheets downwardly between them. The gears 60 and 60' on the shaft 40 mesh with and drive gears 63 and 63' fixed on the rotative counter shafts 59 and 59' respectively. Gears 62 and 62^a are connected with one of the rotative second-folder rollers 20, and intermeshing gears 62^b are connected with the rollers 20 at their extremities remote from the gear 62. Gears 62' and 62^{a'} are connected with one of the 115 120 125 130

rotative second-folder rollers 20^a, and intermeshing gears 62^b are connected with the rollers 20^a at their extremities remote from the gear 62^b. The gear 61 fixed on the shaft 59 drives the second-folder rollers 20^a in unison and the gear 61' fixed on the shaft 59' drives the second-folder rollers 20^a in unison, to cause the second-folded papers to run downwardly between the rollers. Gears 68^b and 68^{b'} fixed on the rotative shafts 68 and 68^a; mesh with and are driven by the gears 62^a and 62^{a'} to effect timely operation of the creasers. Parallel rotative cylinders 64 and 64^a are situated below the cylinders 7 and 7'. Rotative rollers 70 and 70' are parallel to the cylinders 64 and 64^a. Tapes 16^x run around the cylinder 64 and the roller 70 and between the rollers 8 and 8^a and carry the first-folded sheets downwardly to the left-hand second-folder (Fig. 2) and tapes 16^{x'} run around the cylinder 64^a and the roller 70' and between the rollers 8' and 8^{a'} and convey first-folded sheets downwardly to the right-hand second-folder. A gear 64^b connected with the cylinder 64^a, drives a gear 64^c to rotate the central delivery device 67^x. A gear 67^b connected with one of the folder rollers 20 drives a gear 67^c to rotate the left-hand delivery device 67, and a gear 67^{b'} connected with one of the folder rollers 20^a drives a gear 67^{b'} to rotate the right hand delivery device 67^a. Gears 52 and 52' driven by the gears 50 and 50', drive the gears 53 and 53' to rotate the rollers carrying the tapes 75 and 75', to propel the supplement cuts downward to the main carrier cylinders. Spur gears 54 and 55 are fixed on the shaft of the supplement carrier cylinder 5. The gear 54 meshes with and drives a gear 58 secured on the shaft of the supplement cutter cylinder 4. Integral spur gears 56 and 57 are mounted to slide on a short rotative shaft 57^a. The wheel 56 meshes with and is driven by the broad-face gear 45' which is secured on the rotative shaft 45^a. When the parts are in the position shown in Fig. 13 the wheel 57 is in mesh with the wheel 54 to drive the cylinders 5 and 4 at half-speed, and if the wheels 56 and 57 be slid outward on the shaft 57^a and secured in the proper position, the wheel 56 will mesh with the wheel 55 to drive the cylinders 4 and 5 at full speed. The vertical shaft 42 rotates at full speed 55 and through the instrumentality of the gears 44, 45^b, 45, 49, 48, 50 and 51, drives the main cutter cylinder 6, the main carrier cylinder 7 and the folder rollers 8 and 8^a at full speed; and in like manner the shaft 42' through the instrumentality of the gears 44', 45^{b'}, 45', 49', 48', 50', and 51' drives the main cutter cylinder 6', the main carrier cylinder 7' and the folder rollers 8' and 8^{a'} at full speed. The wheel 49 may be slid outwardly on the shaft 49^a, to place in dis-

use the cylinders 6 and 7; and the wheel 49' may be slid outwardly on the shaft 49^{a'} to place in disuse the cylinders 6' and 7'.

The cylinder 4 has blades 4^c coöperating with cutting woods 5^c on the cylinder 5. The cylinder 4 has pins 4^b adapted to be alternately projected and retracted, and the cylinder 5 has pins 5^b adapted to be alternately projected and retracted and the mechanism is so arranged that when the pins 4^b are effective, the pins 5^b will be ineffective, and when the pins 5^b are effective the pins 4^b will be ineffective. Radial blades 4^c are secured on and extend the full length of the cylinder 4. Shafts 4^a extend the full length of and are mounted to oscillate within the cylinder 4. The pins 4^b are connected with the shafts 4^a. Diametrically opposite arms 4^d are secured on the shafts 4^a by set screws 4^m. Little rollers 4^e turn on pins on the arms 4^d and travel on the circumference of a stationary circular plate 4^k coaxial with the cylinder 4. Diametrically opposite arms 4ⁿ are suitably secured on the shafts 4^a. The brackets 4^f are secured on one end of the cylinder 4. Rods 4^g connected with the arms 4ⁿ slide in holes in the brackets 4^f. Springs 4^h surround the rods 4^g and normally act to keep the pins 4^b retracted. The plate 4^k has an integral cam 4^{k'} one-half the thickness of the plate. By loosening the set screws 4^m the arms 4^d may be placed in such position that either or both of the little rollers 4^e will run entirely around on the circumference of the plate 4^k, 95 or may be set in such position that one will run entirely around on the circumference of the plate 4^k and the other will run part way around on the plate 4^k and part way on the cam 4^{k'}; or may be set in such position that both will run part way around on the plate 4^k and part way on the cam 4^{k'}. During the time the little rollers 4^e are running on the circumference of the plate 4^k the pins 4^b will be retracted; and during the time that the little rollers 4^e are running on the cams 4^{k'} the pins 4^b will be projected. This construction and arrangement of the parts admits of the use of either set, or both sets, of the pins 4^b as may be desired. 105

The cylinder 5 has diametrically opposite cutting-woods 5^c having suitably spaced holes 5^{c'} accommodating the pins 5^b and also has holes 5^{c''} (Fig. 5) adapted to accommodate the projecting ends of the pins 4^b of the cylinder 4, during the time that the blades 4^c are cutting the sheets upon the cutting-woods 5^c. The cylinder 5 is equipped with shafts 5^a, pins 5^b, arms 5^d and 5ⁿ, little rollers 5^e, brackets 5^f, rods 5^g and springs 5^h, exactly the same as like parts of the cylinder 4. The stationary circular plate 5^k is concentric with the cylinder 5 and has an integral raised cam 5^{k'} one-half the thickness of the plate and the little rollers 5^e are 115

adjustable to run on the circumference of the plate 5^b and the cam 5^{b'} in the same manner that the little rollers 4^a are adjustable to run on the plate 4^b and cam 4^{b'}. The cylinders 4 and 5 turn toward each other and two sheets are cut off for each revolution of the cylinders. Strippers 76 serve to strip sheets from the cylinder 4 and strippers 76' serve to strip sheets from the cylinder 5. A 10 guard 77 prevents the sheets from falling away from the cylinder 5. Sheets stripped from the cylinder 4 are carried downward on the tapes 75 and sheets stripped from the cylinder 5 are carried downward on the 15 tapes 75'.

The construction described admits of running one deck at half-speed with supplement plates occupying one half the length of the printing couples and running the 20 other decks at full-speed; and in that case the cylinders 4 and 5 will also run at half-speed and the supplement sheets will all run to one carrier cylinder 7 or 7' as the case may be. If it be desired to produce a paper 25 comprising one section with a supplement and the other without a supplement, the supplement cutter and carrier cylinders 4 and 5 and one deck of the press carrying the supplement web, will run at half-speed and in 30 that case the complete paper may be either in book-form or in sections; and if a paper in sections is produced the insert sheet may be between the inside leaves at the center of the paper or may be between any other two 35 leaves of the paper. After the inserting of the supplement sheet the operation will be exactly as already described. In case of alternate run of the supplement sheets the carrier cylinders 7 and 7' will both be in 40 use, all mechanism running at full-speed, and the supplement sheets will run next to the surface of the carrier cylinders, and if papers comprising collected or assembled sections are produced, each section will have 45 a supplement.

A revoluble roller Z supports the group L of associated web-members and a similar roller Z' supports the group R of associated web-members. Pulling wheels K coöperate 50 with the roller Z and similar pulling wheels K' coöperate with the roller Z' and the rollers and wheels serve to propel oppositely the groups of associated webs. Revoluble main cutter cylinders 6 and 6' are equipped with 55 retractive blades 6^a cutting on the cutting-woods M¹⁴ of the cylinders 7 and 7' respectively to cut the associated main web-members into two-leaf sheets.

In order to avoid premature cutting of 60 the webs the cutter mechanisms must be so constructed and arranged that the blades will be effective to cut the sheets at the instant required, but at all other times will be retracted within the circumference of the

cutter cylinders, so that they cannot injure 65 the sheets traveling on the cylinder.

The cutter cylinders 6 and 6' are exactly alike, so a description of one will suffice for both. The cylinder 6 (Figs. 10 and 11) is secured on a shaft 6^b which turns in suitable 70 bearings on the main frame. A circular plate 6^a co-axial with the cylinder is secured on the main frame near one end of the cylinder and has a channel 6^c adapted to guide a little roller 6^a running in the channel. A 75 shaft 6^b extends lengthwise through and oscillates in suitable bearings on the cylinder. Arms 6^d are secured on the shaft 6^b and have a hinge connection with the blades 6^m. An arm 6^e is secured to the shaft 6^b and has a 80 little roller 6^e fitting in the channel 6^c of the plate 6^a. Rubber strips 6^m extend lengthwise along each side of the blade and are held in place by plates 6ⁿ; and the blade, the plates and the strips are connected with 85 each other by bolts 6^o. When the cylinder 6 revolves, the little rollers 6^a running in the channel 6^c and traveling on the cam 6^{b'} impart a reciprocating movement to the arm 6^e which causes the blades 6^m to be projected at 90 the proper instant to cut against a suitably placed cutting-wood on the main carrier-cylinder and after the cutting to cause the immediate retraction of the blade.

Two-leaf sheets cut off by the cylinder 6 95 will be carried around on the cylinder 7 and will be folded centrally by the folder blades M¹⁴ co-acting with the rotating folder rollers 8, 8^a. The sheets cut off by the cylinder 6' will be carried around on the cylinder 7' and 100 will be folded centrally by the folder blades M¹⁴ co-acting with the rollers 8', 8^{a'}. First folded sheets folded by the rollers 8 and 8^a will be carried downward on the left-hand tapes 16^a and the sheets folded by the rollers 105 8' and 8^{a'} will be carried downward on the right-hand tapes 16^{a'}. If the switches 69 be set so that their points will occupy the circumferential grooves on both cylinders 64 and 64' all the first-folded sheets from both 110 pairs of folder rollers will drop onto the central delivery device 67. If the points of the switches 69 be withdrawn from the grooves around both cylinders 64 and 64' the first-folded sheets running on the cylinder 64 will go to the left-hand second-folder mechanism and the first-folded sheets running on the cylinder 64' will go to the right-hand second-folder mechanism; or if the 115 switches 69 be set so that the points of both switches will lie in the grooves around the cylinder 64' all the first-folded sheets from both pairs of folder rollers will run to the left-hand second-folder mechanism and if the points of both switches be set so that 120 their points will occupy the grooves around the cylinder 64 the first-folded sheets from both pairs of first-folder rollers will go to 125.

the right-hand second-folder mechanism. The sheets given the second-fold by the blade 68 and the rollers 20 will drop onto the left-hand delivery device 67^x and the sheets given the second-fold by the blade 68^a and the rollers 20^a will drop onto the right-hand delivery device 67^a.

Revolute pasters 45^b and 45^{b'} situated between the face-to-face groups of associated web-members running to the opposite main carriers serve to apply paste in a continuous strip along the margin between the pages of the upper-most web-members of the groups of main web-members associated on the carriers 6 and 6' respectively, so that the supplement sheets running alternately to the carriers will be respectively pasted on the main sheets with which they are to be folded.

Right and left and opposite main carrier cylinders 7 and 7' in length equal to the length of one page plus margins, are located between the groups R and L of web-members. The cylinder 7' rotates clockwise and the cylinder 7 rotates counter-clockwise. The cylinders 7 and 7' have rotating folder blades M⁴ pins M⁷ adapted to be projected or retracted; and cutting-woods M¹⁴. Rotating folder rollers 8 and 8^a coöperate with the main carrier cylinder 7 and similar folder rollers 8' and 8^{a'} coöperate with the main carrier cylinder 7'. Parallel revolute associating rollers 64 and 64^a are centrally located below the main carrier cylinders 7 and 7'. Revolute rollers 70 and 71 are parallel to the roller 64, and similar rollers 70' and 71' are parallel to the roller 64^a. Tapes 16^x run around the rollers 8^a, 64, 71 and 70 as shown, and similar tapes 16^a run around the rollers 8', 64^a, 71' and 70'. The tapes 16^x carry first-folded sheets, running with the first-folded edge in the lead, between the folder rollers 8 and 8^a and the tapes 16^a carry first-folded sheets running with the folded edge in the lead between the folder rollers 8' and 8^{a'}.

Stationary V-shaped plates 69^e substantially conforming to the curvature of the rollers 64 and 64^a have at their lower ends notches 69^e (Fig. 6) traversed by the points of the switches 69 when the switches are turned as hereinafter explained. The switches 69 are mounted on shafts 69^a and are shaped to conform to the curvature of the rollers 64 and 64^a. The points of the switches 69 fit in corresponding channels around the rollers 64 and 64^a. The shaft 69^a may be turned to cause the points of the switches to enter the channels in the rollers or to cause them to withdraw from the channels, and when the switches are set the shafts may be secured by suitable securing devices 69^a to hold them in position. Pivoted switches 69 are adjacent to the rollers 64 and 64^a respectively. Delivery wheels 67 ro-

tate under the switches 69. Fig. 7 illustrates such a setting of the switches that the first-folded papers traveling with the first-folded edges in the lead, passing around and between the rollers 64 and 64^a will drop directly onto the delivery wheel 67. Fig. 8 illustrates such a setting of the switches that first-folded papers from both of the cylinders 7 and 7' will run over the right-hand switch 69 with the first-folded edges in the lead to the right-hand creasing and folding devices 68^a and 20^a and Fig. 9 illustrates such a setting of the switches that first-folded sheets from cylinder 7 will run over the left-hand switch 69 with the first-folded edges in the lead to the right-hand creasing and folding devices 68^a and 20^a. Guards 69^a serve to prevent displacement of the first-folded papers carried on the tapes 16^x and 16^a.

If the points of the switches 69 be turned upward into the grooves around the cylinder 64 as shown in Fig. 8, first-folded papers from both sets of first-folder rollers will run to the right-hand second-folder mechanism; and vice-versa if the points of the switches 69 be set to run in the grooves around the cylinder 64^a, first-folded papers from both sets of first-folder rollers will run to the left-hand folder mechanism; and if the switches be set so that the point of one switch will run in the grooves around the roller 64 and the point of the other switch will run in the grooves around the roller 64^a as shown in Fig. 7, first-folded papers from both sets of first-folder rollers will drop two at a time on to the central delivery device 67.

The important feature of this invention is the adaptability to run different combinations with less plate area than under the old system. What I mean is: two plate cylinders, two impression cylinders and two inking devices on the same level, or deck, say the top deck, can perfect two webs on both sides on the same deck; each web will be in width equal to the length of one page plus margins; one of the webs will be a supplement web, taking four stereotyped plates to print on both sides of the web under all conditions; the other web printed on the same level or deck will run edge-to-edge with the first main web.

The second main web will comprise the pages of a four-page paper printed from four stereotyped plates. The supplement web and the main web will run edge-to-edge on the same level, or deck, so the webs will be turned on separate turners, which will give each web a quarter turn and change the position of each web, so they will run face-to-face; and both webs will be in the right

position to run through the single-width cutter and first-folder devices.

The printing press, the slitter device, or slitter devices, the turners, the supplement cutting cylinders, the main cutting cylinders and the first-folder devices are all in such position relative to each other that when a supplement web is used, and after making the quarter turn, the supplement web will run to the supplement cutting cylinders so situated that the supplement sheets will always come on the inside of the main webs, or web-members, after they make the quarter turn; this is true if two supplements are used, or if one supplement is used.

The supplement cutters are positioned to coöperate with one main cutter and one folder device, or to coöperate with two main cutters and two folder devices. To produce two complete papers for each revolution of the main printing couples the supplement cutter cylinders will run at full-speed and the supplement sheets will run alternately to the folder devices; in that case two plate cylinders having two plates on each plate cylinder will be used to print both sides of the supplement web. If the supplement cutter is operated at half-speed and one cutter, device and one folder device be used, the supplement sheets will be printed by four plates on two plate cylinders and will all go to one folder device.

Another practical advantage is that the machine is adapted to print main pages and supplement pages with all the plate cylinders in use and covered with printing matter. The position of the supplement cutter between the diverged members of a composite web, admits of leading the supplement web-member to the supplement cutter device, to be cut into sheets in length equal to the width of one page plus margins, the cut sheets going alternately to the coöperating folder devices; and leading the other member or members of the same web to one of the main cutter devices to be cut into sheets in length equal to the width of two pages plus margins running to one of the folder devices.

The machine is also adapted to print a newspaper or a magazine without using duplicate plates, either in book-form or in sections. The only time that duplicate plates need be used is when a two-page supplement sheet is printed; in that case the effective plates will occupy four-page plate-area on the two plate cylinders, and never any more nor any less.

When operating to produce a fourteen page paper printed by fourteen plates and folded at each revolution of the plate cylinders four full-speed plate cylinders on two decks will be used. One main web comprising the matter of main pages exclusively will be printed by two plate cylinders on one deck and one composite web comprising the

matter of main pages and supplement pages will be printed by two plate cylinders on the other deck. The printed webs will be associated and the slitter 24 will slit the associated webs lengthwise to form three main web-members and one supplement web-member, and the web-members will be turned on the turners P to dispose the web-members in single alinement with the supplement web-member between main web-members. The two left-hand main web-members running from the left-hand turner P (Fig. 2.) will run around the left-hand roller Z. The supplement web-member and one right-hand main web-member running from the right-hand turner P will run around the right-hand roller Z', and thence to and around the left-hand roller Z and will be associated with the left-hand main web-members running thereon, the supplement web-member being next to the roller Z. The supplement web-member will run to the cylinders 4 and 5 by which it will be cut into sheets in length equal to the width of one page plus margins. One sheet cut from the supplement web-member will be carried by the tapes 73 to the left-hand cylinder 7 and the next succeeding sheet cut from the supplement web-member and running to and on the right-hand tapes 75 will run to and around the cylinder 7', and thence on the right hand tapes 16* to the central delivery device 67* parallel to the cylinders 4 and 5. The associated main web-members running on the left-hand roller Z will run to and between the cylinders 6 and 7 and will be cut into sheets in length equal to the width of two pages plus margins and the one-leaf supplement sheet forwarded by the left-hand tapes 75 will in succession be inserted with the two-leaf main sheets and the two-leaf main sheets carried on the cylinder 7 will run to and be folded centrally by the left-hand folder rollers 8 and 8* to produce a fourteen page paper printed by fourteen plates and folded at each revolution of the plate cylinders. To produce one-leaf insert sheets to be inserted with two-leaf main sheets going to one folder, the supplement web will be printed by two plate cylinders and will be forwarded to the full-speed cutter cylinders 4 and 5 which will make two cuts at each revolution of the plate cylinders and the one-leaf cuts running from one half-circumference of the plate cylinders will be inserted with the main two-leaf cuts running on one carrier cylinder and the one-leaf cuts running from the other half-circumference of the same plate cylinders will run around the other carrier to the central delivery device 67* in line with the rotary folders.

The expression, "leading pages", used in the claims means the two pages of each four page main sheet, (one page on each side of the sheet), which are at the leading end of

the web as it runs to the main cutter. The expression, "leading ends of the sheets", used in the claims, means,—the ends of the four-page main sheets which are in the lead as the sheets run on the main carrier cylinders.

Having fully described my invention, what I claim as new and desire to secure by Letters Patent is:

10. 1. The combination of printing means operable at either one of two different speeds to print a two-page wide web; means for slitting the web to form web-members; opposite turners and web-forwarding means adapted to turn the web-members to cause them to run at right angles to their initial line of travel and toward a common center; a single-width cutter intermediate of and in line with said web-forwarding means and operable at either one of two different speeds to make two cuts for each revolution of the printing means; and two opposite carriers jointly effective to carry cuts running from the cutter to the carriers alternately when the cutter is operating at either speed, and either one singly effective to carry all the successive cuts when the cutter is operating at the slower speed.
2. The combination of printing means comprising a plurality of plate cylinders two pages in circumference and a plurality of pages in width and adapted to print both sides of a plurality of continuously moving webs; web-forwarding and slitting means adapted to forward and slit the printed webs; turners effective to turn the web-members to dispose them face to face in single-width alinement; second forwarding devices at right angles to said first named web-forwarding means and adapted to forward the turned web-members; two opposite rotary folders in line with said second web-forwarding devices; two rotary cutter cylinders positioned to cut sheets to go to either rotary folder or both rotary folders; sheet-holding devices and cutting devices on said cutter cylinders; means controlling the sheet-holding devices; and leaders effective to lead to one rotary folder the cuts comprising matter printed by one set of plates occupying one half-circumference of the plate cylinders and to lead to the other rotary folder cuts comprising matter printed by one set of plates occupying the other half-circumference of the same plate cylinders.
3. In an apparatus of the class described, the combination of two plate cylinders two pages in width and two pages in circumference and equipped with plates having columns lengthwise of the plate cylinders and adapted to print both sides of a main web in width equal to the length of two pages plus margins; two plate cylinders two pages in circumference and equipped with plates occupying a space in width equal to the length of one page plus margins on each plate cylinder and having columns lengthwise of the plate cylinders and adapted to print both sides of a single-width supplement web; means for slitting the main web; means for effecting a quarter-turn of the web-members to dispose them in single alinement face-to-face; a half-speed supplement cutter between the alined main web-members; means for effecting a quarter-turn of the supplement web and forwarding it to the supplement cutter between the alined main web-members; a full-speed main cutter adapted to cut the main web-members into sheets in length equal to the width of two pages plus margins; means for forwarding the main web-members to the main cutter; means for inserting a supplement sheet between the main sheets cut by the main cutter; and a folder adapted to fold the main sheets centrally, including a supplement sheet in each paper to produce a complete ten-page book-form paper printed by twelve plates at each revolution of the main plate cylinders.
4. In an apparatus of the class described, in combination with printing, associating and slitting means; two turners adapted to turn main web-members and a supplement web-member between the main web-members; a rotary supplement cutter below the turners adapted to cut the supplement web-member into one-leaf supplement sheets; main cutters adapted to cut the main web-members into two-leaf main sheets; and two rotary folders adapted to fold papers comprising two-leaf main sheets cut by the main cutters and one-leaf supplement sheets cut by the supplement cutter.
5. The combination of plate cylinders a plurality of pages in width, two pages in circumference and equipped with plates having columns lengthwise of the plate cylinders and adapted to print on a plurality of webs at each revolution of the plate cylinders all the pages of a complete paper including two-page inserts, by means of one set of plates for main pages of each paper, and two plates for each two-page insert; means for slitting the web to form web-members edge to edge; two turners in line with the main web-members effective to turn the web-members to run face to face; means for forwarding the insert web; means for disposing the quarter-turned insert web between the two turners; a pair of full-speed cutting cylinders below the turners and adapted to cut the insert web into sheets in length equal to the width of one page plus margins; two opposite main cutters, one on each side of the insert cutter and making one cut at each revolution of the plate cylinders to cut the main web-members into sheets in length equal to the width of two pages.

5 pages plus margins; means for inserting the insert cuts with the main cuts; two rotary folders adapted to make the first fold of the main cut; means for assembling the first-folded cuts running in a straight line; and a second folder adapted to fold together all the first folded cuts, to produce at each revolution of the plate cylinders a complete second-folded paper comprising main pages 10 printed by one set of main plates and insert pages printed by two plates for each insert sheet.

6. The combination of printing means adapted to perfect on both sides of continuously moving parallel webs the matter of main pages in rows with columns cross-wise of the webs and the matter of supplement pages in rows with columns cross-wise of a web-member; means for slitting the webs 15 length-wise between the rows of pages to divide the webs into two edge-to-edge groups of web-members comprising main web-members in both groups, and a supplement web-member in one group; means for effecting 20 a quarter turn of all the web-members to dispose face-to-face the groups of web-members originally running edge-to-edge; a supplement cutter between the face-to-face groups of web-members; means for leading 25 the supplement web-member to said supplement cutter; a main carrier coöoperating with the supplement cutter; means for associating on the main carrier web-members from both groups and associating therewith 30 sheets cut from the supplement web-member; a main cutter adapted to cut into two-leaf sheets the associated main web-members on said main carrier; a first folder adapted to fold centrally said two-leaf sheets, to 35 40 form first-folded papers; and a second folder adapted to make the second fold of said papers.

7. The combination of printing means adapted to perfect on both sides of continuously moving parallel webs the matter of main pages in rows with columns cross-wise of the webs and the matter of supplement pages in rows with columns cross-wise of a web-member; means for slitting the webs 45 length-wise between the rows of pages to divide the webs into two edge-to-edge groups of web-members comprising main web-members in both groups, and a supplement web-member in one group; means for 50 effecting a quarter turn of all the web-members to dispose face-to-face, the groups of web-members originally running edge-to-edge; a supplement cutter between the face-to-face groups of web-members; means for 55 leading the supplement web-member to said supplement cutter; a main carrier coöperating with the supplement cutter; means for associating on the main carrier web-members from both groups and associating therewith sheets cut from the supplement web- 60

member; a main cutter adapted to cut into two-leaf sheets the associated main web-members on said main carrier; a first folder adapted to fold centrally said two-leaf sheets, to form first folded papers; a second 70 folder adapted to make the second fold of said papers and a delivery device adapted to receive said second folded papers.

8. The combination of means for forwarding a web to the cutting cylinders; two 75 co-acting cutting cylinders rotative at either one of two different speeds and each having two diametrically opposite cutter-elements co-acting with the complementary cutter elements on the complementary cutting cylinder 80 to cut off sheets in length equal to the width of one page plus margins; sheet-holding devices on each cylinder diametrically opposite to each other and respectively adjacent to the cutter-elements on that cylinder and 85 capable of variable operation; controlling means effective for variable control of the sheet-holding devices on one cutting cylinder; and other controlling means effective for variable control of the sheet-holding devices on the complementary cutting cylinder. 90

9. The combination of main printing means comprising plate cylinders in width equal to the length of two pages plus margins and in circumference equal to the width of two pages plus margins and equipped with exclusively original plates having columns with the length of the columns parallel to the axes of the plate cylinders and adapted to print on both sides of a continuously moving web the matter of main pages in rows with the lengths of the columns crosswise of the web-members; supplement printing means in circumference equal to the width of two pages plus margins and in width equal to the length of one page plus margins and having a supplement printing area of four pages, two supplement plates being on one supplement plate cylinder and two supplement plates being 95 on the complementary plate cylinder; means for slitting the main web; means for effecting a quarter-turn of the main web-members to dispose them in parallel one web-member being on one side of the supplement cutter and the other web-member being on the other side of the supplement cutter; means for effecting a quarter-turn of the supplement web to dispose it between and parallel to the main web-members; a single-width half-speed supplement cutter between the quarter-turned and aligned main web-members; a two-cylinder single-width full-speed main carrier and cutter unit equipped with sheet-cutting means spaced to cut into 100 two-leaf sheets in length equal to the width of two pages plus margins the entire product of the main plate cylinders printed by exclusively original plates for main pages 105 and means adapted to crease said two-leaf 110

115

120

125

130

sheets centrally; means for associating the main web-members on said carrier and cutter unit; means for inserting half-speed one-leaf supplement sheets between the main web-members associated on said main carrier and cutter unit; rotary folder rollers coöperating with said main carrier and cutter unit; and a second folder coöperating with said folder rollers.

10. In an apparatus of the class described, the combination of printing, associating, and slitting means; two turners positioned to turn the members of the slitted webs; two opposite rotary folders below the turners; and a cutter between the turners and the folders and operable at half-speed to sever cuts all going to one folder and operable at full-speed to sever cuts going to two folders alternately.

11. In an apparatus of the class described, in combination with printing, associating, and slitting means; two turners positioned to turn the members of the slitted webs; two opposite rotary first-folders below the turners; a cutter between the turners and the first folders and operable at half-speed to sever cuts all going to either first folder, and operable at full-speed to sever cuts going to the first folders alternately; and a second folder adapted to coöperate with either first folder and likewise adapted to coöperate with both first folders.

12. The combination of printing means comprising plate cylinders two pages in circumference, a plurality of pages in width and adapted to print the matter of rows of pages on both sides of continuously moving webs; means for disposing the rows of pages in single-width alinement; web-forwarding means; parallel rotative co-acting cutter cylinders; cutter means on said cylinders; sheet-holding means on each cylinder adjacent to the cutter means of that cylinder; controlling means controlling the operation of the sheet-holding means to cause all the cuts to run on either cylinder in one direction, or optionally to cause the cuts to run alternately on two cylinders, the cuts on one cylinder going in one direction and the cuts 50 on the other cylinder going in a different direction; means for stripping the cuts from said cylinders respectively, and cut-controlling means controlling the cuts running from said cylinders.

13. In an apparatus of the class described, the combination of printing means comprising four plate cylinders two pages in circumference, two pages in width and having columns lengthwise of the plate cylinders 60 and adapted to perfect on both sides of two parallel continuously moving webs the matter of main pages and supplement pages; means for associating and slitting the webs and forwarding the web-members; means for effecting a quarter-turn of the web-

members to dispose all of them in parallel single alinement; a supplement cutter adapted to cut the supplement web-member into one-leaf sheets; means for forwarding to the supplement cutter one web-member comprising the supplement pages; means for forwarding all the other web-members to one main cutter; a full-speed main cutter making one cut at each revolution of the plate cylinders to cut the main web-members into sheets in length equal to the width of two pages plus margins and in width equal to the length of one page plus margins; means for leading to the folder one sheet cut from the supplement web-member; delivery means parallel to the supplement cutter; sheet-forwarding means between the supplement cutter and the delivery means; and a folder adapted to fold centrally all the two-leaf sheets including one insert sheet in each paper, to produce a fourteen-page book-form paper printed by one set of fourteen plates, and folded at each revolution of the plate cylinders.

14. In an apparatus of the class described, the combination of printing means comprising four plate cylinders two pages in circumference, two pages in width and having columns lengthwise of the plate cylinders and adapted to perfect on both sides of two parallel continuously moving webs the matter of main pages and supplement pages; means for associating and slitting the webs and forwarding the web-members; means for effecting a quarter-turn of the web-members to dispose them in two groups in parallel single alinement; a supplement cutter positioned between the quarter-turned web-members; means for leading to the supplement cutter one web-member comprising the supplement pages; means for forwarding one main web-member to one main cutter; means for forwarding two main web-members to another main cutter; two full-speed main cutters making one cut at each revolution of the plate cylinders to cut the main web-members into sheets in length equal to the width of two pages plus margins and in width equal to the length of one page plus margins; means for propelling the supplement cuts alternately to two folders; and two folders coöperating with the main cutters respectively and adapted to fold the main sheets centrally, including a one-leaf insert sheet in each paper, to simultaneously produce at each revolution of the plate cylinders a six-page paper printed by one set of six plates and a ten-page paper printed by another set of ten plates.

15. In an apparatus of the class described, the combination of printing means comprising six plate cylinders, two pages in circumference, two pages in width and having columns lengthwise of the plate cylinders and adapted to perfect on both sides of three

- parallel continuously moving webs the matter of main pages and supplement pages; means for associating and slitting the webs and forwarding the web-members; means 5 for effecting a quarter-turn of the web-members to dispose them in two groups in parallel single alinement; a supplement cutter positioned between the groups of quarter-turned web-members; means for leading 10 to the supplement cutter one web-member comprising the supplement pages; means for forwarding two associated main web-members to one main cutter; means for forwarding three associated main web-members 15 to another main cutter; two full-speed main cutters making one cut at each revolution of the plate cylinders to cut the main web-members into sheets in length equal to the width of two pages plus margins and in 20 width equal to the length of one page plus margins; means for propelling the supplement cuts alternately to two folders; and two folders coöperating with the main cutters respectively and adapted to fold the 25 main sheets centrally, including an insert sheet in each paper, to simultaneously produce at each revolution of the plate cylinders, a ten-page paper printed by one set of ten plates and a fourteen-page paper printed 30 by one set of fourteen plates.
16. The combination of main printing means comprising plate cylinders in width equal to the length of two pages plus margins and in circumference equal to the width 35 of two pages plus margins and equipped with exclusively original plates having columns lengthwise of the plate cylinders; supplement plate cylinders having printing surfaces in width equal to the length of one 40 page plus margins and in circumference equal to the width of two pages plus margins and each having a supplement printing area of two pages, two supplement plates being on one supplement plate cylinder and 45 two supplement plates being on the complementary plate cylinder; a single-width half-speed supplement cutter adapted to make two cuts for each revolution of the supplement printing cylinders, to cut the supplement 50 web into sheets in length equal to the width of one page plus margins; means for slitting the main web into members in width equal to the length of one page plus margins; means for turning the two main web- 55 members, initially running edge-to-edge, to dispose them face-to-face and with their edges parallel, one main web-member being on one side of the supplement cutter and the other web-member being on the other side of 60 the supplement cutter; means for turning the supplement web to aline it with the main web-members; means for leading the supplement web to the half-speed supplement cutter between the face-to-face main web-members; means for associating the main web- 65 members running from both sides of the supplement cutter; means for inserting one-leaf supplement sheets cut by the half-speed supplement cutter, between face-to-face main web-members running to the main cutter, in 70 position to fold a one-leaf supplement sheet between the two-leaf main sheets of each paper; and a single-width main cutter making one cut for each revolution of the main printing couples to cut into sheets in length 75 equal to the width of two pages plus margins the entire product of the main printing couples printed by exclusively original plates for main pages.
17. The combination of main printing 80 means comprising plate cylinders in width equal to the length of two pages plus margins and in circumference equal to the width of two pages plus margins and having columns lengthwise of the plate cylinders; supplement plate cylinders having printing surface occupying two pages in circumference and in width equal to the length of one page plus margins and having a supplement printing area of four plates, two supplement plates 85 being on one supplement plate cylinder and two supplement plates being on the complementary plate cylinder; a single-width half-speed supplement cutter, adapted to make two cuts for each revolution of the supplement 90 printing means, to cut the supplement web into sheets in length equal to the width of one page plus margins; means for slitting the main web into members in width equal to the length of one page plus margins; means for turning the main web-members, initially running edge-to-edge, to dispose them face-to-face and with their edges parallel, one main web-member being on one 95 side of the supplement cutter and the companion main web-member being on the other side of the supplement cutter; means for turning the supplement web to aline it with the main web-members; means for leading the supplement web to the supplement cutter 100 between the face-to-face main web-members; means for associating the main web-members running from both sides of the supplement cutter; means for inserting successive half-speed one-leaf supplement sheets cut by the 105 supplement cutter, between face-to-face main web-members running to the main cutter; a single-width main cutter adapted to cut into sheets in length equal to the width of two pages plus margins at one cut for each 110 revolution of the main printing couples, the entire product of the printing means, printed by exclusively original plates for main pages; and a single-width folder adapted to fold centrally lengthwise along the margins between the pages, the sheets cut by the main cutter.
18. In an apparatus of the class described, the combination of a plurality of right-hand main printing units adapted to perfect on a 115

plurality of main webs, or web-members, in width equal to the length of one page plus margins the matter of main pages with columns crosswise of the webs, or web-members; a plurality of left-hand main printing units adapted to perfect on a plurality of main webs, or web-members, in width equal to the length of one page plus margins the matter of main pages with columns crosswise of the webs, or web-members; means for associating all the right-hand main webs, or web-members, in a right-hand group; means for associating all the left-hand main webs, or web-members, in a left-hand group, edge-to-edge relative to said right-hand group; means for effecting a single quarter turn of each web, or web-member, to dispose in two face-to-face groups the webs, or web-members, initially running edge-to-edge; means for associating said face-to-face groups of main webs, or web-members; a main carrier adapted to carry the associated face-to-face groups of main webs, or web-members; a main cutter adapted to cut into two-leaf sheets said associated groups of webs, or web-members; a first-folder adapted to fold said sheets centrally to form book-form papers; and a second folder adapted to make the second-fold of said papers.

19. The combination of main printing means comprising plate cylinders in width equal to the length of two pages plus margins and in circumference equal the width of two pages plus margins and having columns lengthwise of the plate cylinders; supplement plate cylinders having printing surface in circumference equal to the width of two pages plus margins and in width equal to the length of one page plus margins and having a supplement printing area of four pages, two supplement plates being on one supplement plate cylinder and two supplement plates being on the complementary plate cylinder; a single-width half-speed supplement cutter, adapted to make one cut for each half-revolution of the supplement printing means, to cut the supplement web into sheets in length equal to the width of one page plus margins; means for slitting the main web into members in width equal to the length of one page plus margins; means for turning the main web-members, initially running edge-to-edge, to dispose them face-to-face and with their edges parallel, one main web-member being on one side of the supplement cutter and the companion main web-member being on the other side of the supplement cutter; means for turning the supplement web to align it with the main web-members; means for leading the supplement web to the supplement cutter between the face-to-face main web-members; means for associating the main web-members running from both sides of the supple-

ment cutter; means for inserting successive half-speed one-leaf supplement sheets cut by the supplement cutter, between face-to-face main web-members running to the main cutter; a single-width full-speed main cutter adapted to cut into sheets in length equal to the width of two pages plus margins at one cut for each revolution of the main printing couples, the entire product of the main printing means, printed by exclusively original plates for main pages; a first folder adapted to fold centrally along the margin between the pages, the sheets cut by the main cutter; and a second folder adapted to fold the first-folded sheets transversely to the crease of the first fold.

20. The combination of a half-speed single-width supplement cutter adapted to cut a supplement web into sheets in length equal to the width of one page plus margins; means for forwarding a single-width half-speed supplement web to the supplement cutter; means for forwarding one full speed single width main web on one side of the supplement cutter to a full speed main cutter and forwarding another full speed single-width main web on the other side of the supplement cutter to the same main cutter; a full speed single width main cutter and a full speed single width rotary folder adapted to cut into sheets in length equal to the width of two pages plus margins the single width webs running on both sides of the supplement cutter, and fold said sheets; means for leading the supplement web in position to be guided between the downwardly running main webs before cutting off the supplement sheet; sheet-folding means effective to take and hold the leading ends of the associated main webs and the leading end of the supplement sheet before cutting off the main sheets; and a second folder adapted to make the second fold across the crease of the first fold.

21. In combination with two opposite single-width full-speed main cutters adapted to cut major sheets and a single-width complementary cutter operable at full-speed or optionally at half-speed to cut minor sheets; two opposite single-width full-speed folders operating to fold major sheets centrally and means for leading all the minor sheets at half-speed from the complementary cutter to one folder, or leading alternate minor sheets at full-speed to two folders.

22. The combination of plate cylinders a plurality of pages in width, two pages in circumference and equipped with plates having columns lengthwise of the plate cylinders and adapted to print on a plurality of webs at each revolution of the plate cylinders all the pages of a complete paper including two page inserts, by means of one set of plates for main pages of each paper and two plates for each two page insert;

means for slitting the webs to form web-members edge to edge, two opposite turners effective to turn the web-members to run between the turners with the web-member comprising the insert pages between the main web-members running on the turners; a cutter between the turners and making two cuts at each revolution of the plate cylinders to cut the insert web-member into sheets in length equal to the width of one page plus margins; two opposite main cutters, one on each side of the supplement cutter and making one cut at each revolution of the plate cylinders to cut the main web-members into sheets in length equal to the width of two pages plus margins, means for inserting the insert cuts with the main cuts; two rotary folders adapted to make the first fold of main sheets cut by said main cutters; means for assembling the first-folded sheets; and a second folder adapted to fold together the first folded sheets, to produce at each revolution of the plate cylinders a complete second-folded paper comprising main pages printed by one set of main plates and insert sheets printed by two plates for each insert sheet.

23. In an apparatus of the class described, the combination of means for printing, associating, and forwarding a plurality of webs, or web-members; a cutter comprising two rotative co-acting cylinders; two diametrically opposite sets of sheet-holding means on each cylinder; controlling means effective for variable control of the sheet-holding means; means for stripping the cuts from the cylinders; leaders adapted to lead the cuts away from the cylinders; a delivery device parallel to the cutter cylinders and positioned to receive the cuts running from the leaders; and means for propelling the cuts from the leaders to the delivery device.

24. The combination of a half-speed single-width supplement cutter adapted to cut a single-width supplement web into sheets in length equal to the width of one page plus margins; means for forwarding a half-speed supplement web to the supplement cutter; means for forwarding one single-width full-speed main web on one side of the supplement cutter to a full speed main-cutter and forwarding another single width full-speed main web on the other side of the supplement cutter to the same main cutter; a full speed single-width main cutter and a full-speed single-width rotary folder, adapted to cut, into sheets in length equal to the width of two pages plus margins, single-width main webs running on both sides of the supplement cutter, and fold said sheets; means for leading the supplement web in position to be guided between the downwardly running main webs before cutting off the supplement sheet; sheet holding means adapted to take and hold the leading ends of the as-

sociated main webs, before cutting off the main sheets; and a second-folder adapted to make the second fold across the crease of the first fold.

25. In combination with a single-ender printing machine; a single-width half-speed supplement cutter, a single width full speed main cutter, a single width full speed rotary folder and a second folder at right angles to said rotary folder, all at one end of the printing machine; means for forwarding a half-speed single-width supplement web to the supplement cutter; means for forwarding one single-width main web on one side of the supplement cutter to the main cutter and forwarding another single-width main web on the other side of the supplement cutter to the main cutter; sheet holding means adapted to take and hold the leading ends of the main webs to lead them downwardly; and means for leading the supplement web into position to be guided between the downwardly running main webs before cutting off the supplement sheet.

26. A printing mechanism having a plate area of four supplement plates; in combination with a plurality of main printing mechanisms each two plates in circumference and having a plate area of four main plates and adapted to perfect both sides of a single-width web or web-member; means for associating into two groups edge-to-edge the perfected webs or web-members; means for effecting a single quarter-turn of the web-members to dispose in two face-to-face groups the webs or web-members, initially running edge-to-edge; and a half-speed supplement cutter between the face-to-face groups of web-members and adapted to cut the supplemental web-member into one-leaf sheets.

27. In apparatus of the class described, the combination of a main printing unit adapted to perfect on a continuously moving web the matter of main pages with columns crosswise of the web; a supplement printing unit adapted to perfect on the same web the matter of supplement pages end-to-end with respect to the main pages on said web and having columns crosswise of the web; means for slitting said web to form a main web-member and a supplement web-member; a plurality of right-hand main printing units adapted to perfect a plurality of right-hand main webs, or web-members, in width equal to the length of one page plus margins; a plurality of left-hand main printing units adapted to perfect a plurality of main webs, or web-members, in width equal to the length of one page plus margins; means for associating in a right-hand group in width equal to the length of one page plus margins all the right-hand main webs, or web-members; means for associating in a left-hand main group in width equal to the length of one

- page plus margins all the left-hand main webs, or web-members; half speed supplement cutter and carrier mechanism between and in range with said right-hand and left-hand groups of webs, or web-members; 5 means for propelling said supplement web-member to said supplement cutter mechanism between said right-hand and left-hand groups of webs, or web-members; a main carrier coöperating with said supplement cutter and carrier mechanism; means for associating said right-hand and left-hand groups of main webs, or web-members on said main carriers; means for inserting 10 between a right-hand web, or web-member, and a left-hand web, or web-member, running on said main carrier, a one-leaf supplement sheet for each paper and a main cutter adapted to cut into two-leaf sheets the 15 associated right-hand and left-hand webs, or web-members, running on said main carrier.
28. In an apparatus of the class described, the combination of a supplement printing 25 unit having an area of four plates and adapted to print on a supplement web, in width equal to the length of one page plus margins, the matter of supplement pages having columns crosswise of the web; a plurality of right-hand main printing units 30 adapted to perfect on a plurality of right-hand main webs, or web-members, in width equal to the length of one page plus margins, the matter of main pages having columns crosswise of the webs, or web-members; 35 means for associating in a right-hand group, in width equal to the length of one page plus margins, all the perfected right-hand main webs, or web-members; means for associating in a left-hand group, in width equal to the length of one page plus margins, and edge-to-edge relative to said right-hand group, all the perfected left-hand 40 main webs, or web-members; means for effecting a single quarter-turn of each web in width equal to the length of one page plus margins, or of each web-member in width equal to the length of one page plus margins, the matter of main pages having columns crosswise of the webs, or web-members; 45 means for associating in a left-hand group, in width equal to the length of one page plus margins, and edge-to-edge relative to said right-hand group, all the perfected left-hand main webs, or web-members; means for effecting a single quarter-turn of each web in width equal to the length of one page plus margins, or of each web-member in width equal to the length of one page plus margins, to dispose in two face-to-face groups the main webs, or web-members, initially running edge-to-edge; a half-speed supplement cutter between the face-to-face groups of associated main web-members; means for leading the supplement web to said supplement cutter; a single-width main carrier coöperating with said supplement cutter; means for associating said face-to-face groups of main webs, or web-members, on said main carrier; means for inserting one-leaf sheets 55 cut by said supplement cutter between the face-to-face webs, or web-members, running on said main carrier; a single-width full-speed main cutter adapted to cut into two-leaf sheets, the right-hand main webs, or web-members and the left-hand main webs, or web-members, associated on said carrier and a single-width first-folder and a single-width second folder coöperating with said main carrier.
30. In an apparatus of the class described, the combination of a supplement printing 60

- unit having an area of four plates and adapted to print on a supplement web, in width equal to the length of one page plus margins, the matter of supplement pages 5 having columns crosswise of the web, or web-member; a plurality of right-hand main printing units adapted to perfect on a plurality of right-hand main webs, or web-members in width equal to the length of one page plus 10 margins, the matter of main pages having columns crosswise of the webs, or web-members; means for associating in a right-hand group, in width equal to the length of one page plus margins, all the perfected right-hand main webs, or web-members; means for associating in a left-hand group, in 15 width equal to the length of one page plus margins, and edge-to-edge relative to said right-hand group, all the perfected left-hand main webs, or web-members; means for effecting a single quarter-turn of each 20 web in width equal to the length of one page plus margins, or of each web-member in width equal to the length of one page plus margins, to dispose in two face-to-face groups the main webs, or web-members, initially running edge-to-edge; a half-speed supplement cutter between the face-to-face groups of associated web-members; means for leading the supplement web to said supplement cutter; a full-speed single-width main carrier coöperating with said supplement cutter; means for associating said face-to-face groups of main webs, or web-members, on said main carrier; means for inserting one-leaf sheets cut by said supplement cutter between face-to-face main webs, or web-members, running on said main carrier; a full-speed single-width main cutter adapted to cut into two-leaf sheets the right-hand main webs, or web-members and the left-hand main webs, or web-members; associated on said carrier; and a first-folder and a delivery device coöperating with said main carrier.
32. In an apparatus of the class described, the combination of a supplement printing unit having an area of four plates and adapted to print on a supplement web, the matter of supplement pages, having columns crosswise of the web; a plurality of right-hand main printing units adapted to perfect on a plurality of right-hand main webs, or web-members, the matter of main pages having columns crosswise of the webs, or web-members; a plurality of left-hand printing units adapted to perfect on a plurality of right-hand main webs, or web-members, the matter of main pages having columns crosswise of the webs, or web-members; means for associating in a right-hand group in width equal to the length of one page plus margins, all the perfected right-hand main webs, or web-members; means for associating in a left-hand group, in 10 width equal to the length of one page plus margins, and in range with said right-hand group all the perfected left-hand main webs, or web-members; half-speed supplement cutter mechanism, between and in range with the right-hand and left-hand 15
31. In an apparatus of the class described, the combination of a supplement printing unit having an area of four plates and adapted to print on a supplement web, in width equal to the length of one page plus margins, the matter of supplement pages having columns crosswise of the web; a plurality of right-hand main printing units adapted to perfect on a plurality of right-hand main webs, or web-members, the matter of main pages having columns crosswise of the webs, or web-members; a plurality of left-hand printing units adapted to perfect on a plurality of right-hand main webs, or web-members, the matter of main pages having columns crosswise of the webs, or web-members; means for associating in a right-hand group, in width equal to the length of one page plus margins, all the perfected right-hand main webs, or web-members; means for associating in a left-hand group, in width equal to the length of one page plus margins, and in range with said right-hand group all the perfected left-hand main webs, or web-members; half-speed supplement cutter mechanism, between and in range with the right-hand and left-hand 20
- 60
- 65

- groups of associated web-members; means for leading the supplement web to said supplement cutter mechanism; right and left and opposite single-width main carriers adapted to coöperate with said supplement cutter mechanism; means for associating on one main carrier main webs, or web-members, from both of said groups; means for associating on the other main carrier, main webs, or web-members, of one group; means for inserting between the webs, or web-members, from both groups associated on one main carrier, supplement sheets running from said supplement cutter mechanism; and two full-speed single-width main cutters coöperating with said main carriers respectively and adapted to cut into two-leaf sheets the main webs, or web-members running thereon.

33. In an apparatus of the class described, the combination of a supplement printing unit having an area of four plates and adapted to print on a supplement web, the matter of supplement pages, having columns crosswise of the web; a plurality of right-hand main printing units adapted to perfect on a plurality of right-hand main webs, or web-members, the matter of main pages having columns crosswise of the webs, or web-members; a plurality of left-hand printing units adapted to perfect on a plurality of left-hand main webs, or web-members, the matter of main pages having columns crosswise of the webs, or web-members; means for associating in a right-hand group in width equal to the length of one page plus margins, all the perfected right-hand main webs, or web-members; half-speed single-width supplement cutter mechanism between and in range with the right-hand and left-hand groups of associated web-members; means for leading the supplement web to said supplement cutter mechanism; right and left and opposite full-speed single-width main carriers adapted to coöperate with said supplement cutter mechanism; means for associating on one main carrier, webs, or web-members, from both of said groups; means for associating on the other carrier, webs, or web-members, of one group; means for inserting between the webs, or web-members, from both groups associated on one main carrier, one-leaf supplement sheets running from said supplement cutter mechanism; main cutters half-speed single width coöperating with said main carriers respectively; first-folder mechanisms coöperating with said main carriers respectively and second-folder mechanisms coöperating with said first-folder mechanisms respectively.

35. In an apparatus of the class described, the combination of a supplement printing unit having an area of four plates and adapted to print on a supplement web the matter of supplement pages, having columns crosswise of the web, or web-member; a plurality of right-hand main printing units adapted to perfect on a plurality of right-hand main webs, or web-members, the matter of main pages having columns crosswise of the webs, or web-members; a plurality of left-hand printing units adapted to perfect on a plurality of left-hand main webs, or web-members, the matter of main pages having columns crosswise of the webs, or web-members; means for associating in a right-hand group in width equal to the length of one page plus margins, all the perfected right-hand main webs, or web-members; half-speed supplement cutter mechanism, between and in range with the right-hand and left-hand groups of associated web-members; means for leading the supplement web, to said supplement cutter mechanism; right and left and opposite full-speed single-width main carriers adapted to coöperate with said supplement cutter mechanism; means for associating on one main carrier main webs, or web-members from both of said groups; means for associating on the other main carrier, main webs, or web-members of one group; means for inserting between the webs, or web-members, from both groups associated on one main carrier, supplement sheets running from said supplement cutter mechanism; full-speed single-width main cutters coöperating with said main carriers respectively; and first-folder mechanisms coöperating with said main carriers respectively.

36. In an apparatus of the class described, the combination of a supplement printing unit having an area of four plates and adapted to print on a supplement web the matter of supplement pages, having columns crosswise of the web, or web-member; a plurality of right-hand main printing units adapted to perfect on a plurality of right-hand main webs, or web-members, the matter of main pages having columns crosswise of the webs, or web-members; means for associating in a right-hand group in width equal to the length of one page plus margins, all the perfected right-hand main webs, or web-members; means for associating in a left-hand group, in width equal to the length of one page,

- plus margins, and in range with said right-hand group all the perfected left-hand main webs, or web-members; half-speed supplement cutter mechanism between and in range 5 with the right-hand and left-hand groups of associated web-members; means for leading the supplement web to said supplement cutter mechanism; right and left and opposite main carriers adapted to coöperate with said supplement cutter mechanism; means for 10 associating on one main carrier, webs, or web-members, from both of said groups; means for associating on the other main carrier, webs, or web-members, of one group; means for inserting between the webs, or 15 web-members, from both groups associated on one main carrier, one-leaf supplement sheets running from said supplement cutter mechanism; main cutters coöoperating with said main carriers respectively; first-folder mechanisms coöoperating with said main carriers respectively; and one second-folder mechanism coöperating with both first-folder 20 mechanisms.

36. In an apparatus of the class described, the combination of a supplement printing unit having an area of four plates and adapted to print on a supplement web, or web-member, in width equal to the length 25 of one page plus margins, the matter of supplement pages having columns crosswise of the web a plurality of right-hand main printing units adapted to perfect on a plurality of right-hand main webs, or web-members, in width equal to the length 30 of one page plus margins, the matter of main pages having columns crosswise of the webs, or web-members; a plurality of left-hand printing units adapted to perfect on a plurality of left-hand main webs, or web-members, in width equal to the length 35 of one page plus margins, the matter of main pages having columns crosswise of the webs, or web-members; means for associating in a right-hand group, in width equal to the length 40 of one page plus margins, all the perfected right-hand main webs, or web-members; means for associating in a left-hand group in width equal to the length of one page plus margins and edge-to-edge relative to 45 said right-hand group, all the perfected left-hand webs, or web-members; means for effecting a single quarter turn of each web in width equal to the length of one page plus margins, or of each web-member in width equal to the length of one page plus 50 margins, to dispose in two face-to-face groups the webs, or web-members, initially running edge-to-edge; a supplement cutter between the face-to-face groups of associated webs, or web-members; means for leading the supplement web, or web-member, to said supplement cutter; right and left and opposite main carriers coöperating with said supplement cutter; main cutters coöperating with said main carriers respectively; means for propelling to said main carriers alternately, sheets cut by said supplement cutter; first-folder mechanisms coöperating with said main carriers respectively; and one second-folder mechanism coöperating with both first-folder mechanisms.

37. In an apparatus of the class described, the combination of a supplement printing unit having an area of four plates and adapted to print on a supplement web, or web-member, in width equal to the length 55 of one page plus margins, the matter of supplement pages having columns crosswise of the web a plurality of right-hand main printing units adapted to perfect on a plurality of right-hand main webs, or web-members, in width equal to the length of one page plus margins, the matter of main pages having columns crosswise of the webs, or web-members; a plurality of left-hand printing units adapted to perfect on a plurality of left-hand main webs, or web-members, in width equal to the length 60 of one page plus margins, the matter of main pages having columns crosswise of the webs, or web-members; means for associating in a right-hand group, in width equal to the length of one page plus margins, all the perfected right-hand main webs, or web-members; means for associating in a left-hand group in width equal to the length of one page plus margins and edge-to-edge relative to 65 said right-hand group, all the perfected left-hand webs, or web-members; means for effecting a single quarter turn of each web in width equal to the length of one page plus margins, or of each web-member in width equal to the length of one page plus margins, to dispose in two face-to-face groups the webs, or web-members, initially running edge-to-edge; a supplement cutter between the face-to-face groups of associated webs, or web-members; means for leading the supplement web, or web-member, to said supplement cutter; right and left and opposite main carriers coöperating with said supplement cutter; main cutters coöperating with said main carriers respectively; means for propelling to said main carriers alternately, sheets cut by said supplement cutter; first-folder mechanisms coöperating with said main carriers respectively; and one second-folder mechanism coöperating with both first-folder mechanisms.

38. In an apparatus of the class described, the combination of a supplement printing unit having an area of four plates and adapted to print on a supplement web, or web-member, in width equal to the length 70 of one page plus margins, the matter of supplement pages having columns crosswise of the web a plurality of right-hand main printing units adapted to perfect on a plurality of right-hand main webs, or web-members, in width equal to the length of one page plus margins, the matter of main pages having columns crosswise of the webs, or web-members; a plurality of left-hand printing units adapted to perfect on a plurality of left-hand main webs, or web-members, in width equal to the length 75 of one page plus margins, the matter of main pages having columns crosswise of the webs, or web-members; means for associating in a right-hand group, in width equal to the length of one page plus margins, all the perfected right-hand main webs, or web-members; means for associating in a left-hand group in width equal to the length of one page plus margins and edge-to-edge relative to 80 said right-hand group, all the perfected left-hand webs, or web-members; means for effecting a single quarter turn of each web in width equal to the length of one page plus margins, or of each web-member in width equal to the length of one page plus margins, to dispose in two face-to-face groups the webs, or web-members, initially running edge-to-edge; a supplement cutter between the face-to-face groups of associated webs, or web-members; means for leading the supplement web, or web-member, to said supplement cutter; right and left and opposite main carriers coöperating with said supplement cutter; main cutters coöperating with said main carriers respectively; means for propelling to said main carriers alternately, sheets cut by said supplement cutter; first-folder mechanisms coöperating with said main carriers respectively; and one second-folder mechanism coöperating with both first-folder mechanisms.

- the web, or web-member; a plurality of right hand main printing units adapted to perfect on a plurality of right-hand main webs, or web-members, in width equal to the length 5 of one page plus margins, the matter of main pages having columns crosswise of the webs, or web-members; a plurality of left-hand printing units adapted to perfect on a plurality of left-hand main webs, or web-members, in width equal to the length of one page plus margins, the matter of main pages having columns crosswise of the webs, or web-members; means for associating in a right-hand group, in width equal to the 10 length of one page plus margins, all the perfected right-hand main webs or web-members; means for associating in a left-hand group in width equal to the length of one page plus margins and edge-to-edge 15 relative to said right-hand groups, all the perfected left-hand main webs, or web-members; means for effecting a single quarter-turn of each web in width equal to the length of one page plus margins, or of each 20 web-member in width equal to the length of one page plus margins, to dispose in two face-to-face groups the webs, or web-members, initially running edge-to-edge; a supplement cutter between the face-to-face 25 groups of associated webs, or web-members; means for leading the supplement web, or web-member, to said supplement cutter; right and left and opposite main carriers co-operating with said supplement cutter; 30 main cutters co-operating with said main carriers respectively; means for propelling to said main carriers alternately, sheets cut by said supplement cutter; first-folder mechanisms co-operating with said main carriers respectively; one second-folder mechanism co-operating with both first-folder mechanisms; and one delivery device co-operating with said second-folder mechanism. 35
- 40 39. In combination with a plurality of main printing mechanisms comprising plate cylinders equipped with plates extending around each plate cylinder a distance equal to the width of two pages plus margins, and extending lengthwise of the plate cylinder a distance equal to the length of two pages plus margins, and having columns lengthwise of the plate cylinder, and impression cylinders co-operating with said plate cylinders to perfect on both sides of continuously moving webs the matter of main pages in rows, said pages being end-to-end with respect to each other and the lengths of the 45 pages being crosswise of the webs; a complementary printing mechanism having on one level plate cylinders having a supplement plate area of four pages and a main plate area of four pages and equipped with plates extending around each plate cylinder a distance equal to the width of two pages 50 plus margins and extending lengthwise of the plate cylinders a distance equal to the length of two pages plus margins, and having columns lengthwise of the plate cylinders, and impression cylinders co-operating with said plate cylinders to perfect on both sides of continuously moving webs the matter of main pages in rows, said pages being end-to-end with respect to each other and the lengths of the pages being crosswise of the webs; half-speed single-width supplement cutter and carrier cylinders located between the groups of quarter-turned web-members; means adapt- 55 60 65 70 75 80 85 90 95 100 105 110 115 120 125 130
40. An apparatus for printing book-form papers by means of exclusively original plates and folding said papers; comprising plate cylinders equipped with plates extending around each plate cylinder a distance equal to the width of two pages plus margins and extending lengthwise of each plate cylinder a distance equal to the length of two pages plus margins, and having columns lengthwise of the plate cylinders, and impression cylinders co-operating with said plate cylinders to perfect on both sides of continuously moving webs, the matter of main pages in rows, said pages being end-to-end with respect to each other and the lengths of the pages being crosswise of the webs; half-speed single-width supplement cutter and carrier cylinders located between the groups of quarter-turned web-members; means adapt- 110 115 120 125 130

ed to effect a single quarter-turn of all the main web-members perfected on one half the length of the plate cylinders to dispose them after making the quarter-turn in one 5 group in single alinement on one side of the supplement cutter and carrier cylinders, and to dispose in another group, in alinement with said first named group, after making the quarter-turn, and on the other 10 side of the supplement cutter and carrier cylinders, all the web-members perfected on the other half of the length of the plate cylinders; a single-width main carrier adapted to carry both groups of associated 15 main web-members; means for associating both groups of web-members on said main carrier; a main cutter adapted to cut into two-leaf sheets in length equal to the width of two pages plus margins the groups of 20 web-members associated on said main carrier; and a folder adapted to fold together said two-leaf sheets along the central margin.

41. An apparatus for printing book-form 25 papers with supplements, by means of exclusively original plates for main pages, and folding said papers; comprising a supplement printing unit having plate cylinders equipped with plates extending around each 30 plate cylinder a distance equal to the width of two pages plus margins and extending lengthwise of each plate cylinder a distance equal to the length of one page plus margins and comprising four pages of plate area 35 and impression cylinders coöperating with said plate cylinders to perfect on both sides of a supplement web in width equal to the length of one page plus margins the matter of pages with columns crosswise of the web; 40 a main printing unit comprising plate cylinders equipped with plates extending around each plate cylinder a distance equal to the width of two pages plus margins and extending lengthwise of each plate cylinder 45 a distance equal to the length of two pages plus margins, and having columns lengthwise of the plate cylinders, and impression cylinders coöperating with said plate cylinders to perfect on both sides of a continuously moving web, the matter of main pages 50 in rows, said pages being end-to-end with respect to each other, and the lengths of the pages being crosswise of the web; means for slitting the main web along the central 55 margin between the ends of the pages; means adapted to effect a quarter-turn of the main web-member perfected on one half the length of the plate cylinders to run on one side of the supplement cutter and carrier 60 cylinders and adapted to effect a quarter-turn of the other main web-member perfected on the other half the length of the plate cylinders to run on the other side of the supplement cutter and carrier cylinders, after making the quarter-turn, and adapted 65 to effect a quarter-turn of other main web-members perfected on the other half the

adapted to effect quarter-turn of the supplement web to run between the quarter-turned and alined main web-members; half-speed supplement cutters and carrier cylinders positioned to cut and carry the supplement web; means for leading the quarter-turned supplement web to the supplement cutter and carrier cylinders; a main carrier cylinder positioned to coöperate with said supplement cutter and carrier cylinders; 70 means for associating on said main carrier cylinder both quarter-turned main web-members; stripping devices and leading devices adapted to strip the supplement sheets from the supplement cutter and carrier cylinders and lead them between the main web-members associated on said main carrier cylinder; a main cutter adapted to cut into two-leaf sheets, in length equal to the width of two pages plus margins, the associated main 75 web-members running on said main carrier cylinder, and a folder adapted to fold together said two-leaf sheets and one-leaf sheets.

42. An apparatus for printing two book-form sections with supplements by means of exclusively original plates for main pages and folding the sections together in the second fold; comprising a supplement printing unit having plate cylinders equipped with 90 plates extending around each plate cylinder a distance equal to the width of two pages plus margins and extending lengthwise of each plate cylinder a distance equal to the length of one page plus margins and comprising 95 four pages of plate area, and impression cylinders coöperating with said plate cylinders to perfect on both sides of a supplement web in width equal to the length of one page plus margins, the matter of 100 pages with columns crosswise of the web; a plurality of main printing units comprising plate cylinders equipped with plates extending around each plate cylinder a distance equal to the width of two pages plus margins, and having columns 105 lengthwise of the plate cylinders, and impression cylinders coöperating with said plate cylinders to perfect on both sides of a continuously moving web the matter of 110 main pages in rows, the pages on each web being end-to-end with respect to each other and the lengths of the pages being crosswise 115 of the webs; means for slitting the main webs along the central margin between the ends of the pages; means adapted to effect a single quarter-turn of the main web-members perfected on one half the length of the 120 main plate cylinders, to run on one side of the supplement cutter and carrier cylinders after making the quarter-turn, and adapted to effect a quarter-turn of other main web-members perfected on the other half the 125

126

- length of the main plate cylinders, to run on the other side of the supplement cutter and carrier cylinders after making the quarter-turn, and adapted to effect a single 5 quarter-turn of the supplement web to run between the groups of quarter-turned and alined main web-members; supplement cutter and carrier cylinders in line with the turned and alined main web-members; 10 means for leading the quarter-turned supplement web to the supplement cutter and carrier cylinders; right and left and opposite main carrier cylinders positioned to coöperate with said supplement cutter and 15 carrier cylinders; means for disposing on one main carrier cylinder one group of quarter-turned main web-members; means for disposing on the other main carrier cylinder the other group of quarter-turned 20 main web-members; stripping devices and leading devices adapted to strip supplement sheets from the supplement cutter and carrier cylinders and lead them alternately to said main carrier cylinders; main cutters co- 25 operating with said main carrier cylinders respectively to cut into two-leaf sheets, in length equal to the width of two pages plus margins, the groups of main web-members running on said main carrier cylinders re- 30 spectively; and first-folders coöperating with said main carrier cylinders respectively to fold said two-leaf sheets along the central margin; means for assembling the first folded sections, and a second-folder 35 adapted to fold together the sections, including supplement in each section.
43. An apparatus for printing two book-form sections, one with supplement and the other without supplement, by means of exclusively original plates for main pages, and 40 folding said sections together in the second fold; comprising a supplement printing unit having plate cylinders equipped with plates extending around each plate cylinder a distance equal to the width of two pages plus margins and extending lengthwise of each plate cylinder a distance equal to the length of one page plus margins and comprising four pages of plate area, and impression cylinders coöperating with said plate cylinders to perfect on both sides of a supplement web, in width equal to the length of one page plus margins, the matter of pages with columns crosswise of the web; a plurality of 50 main printing units comprising plate cylinders equipped with plates extending around each plate cylinder a distance equal to the width of two pages plus margins and extending lengthwise of each plate cylinder a distance equal to the length of two pages plus margins, and having columns lengthwise of the plate cylinders, and impression cylinders coöperating with said plate cylinders to perfect on both sides of continuously 55 moving webs the matter of main pages in 60 rows, the pages on each web being end-to-end with respect to each other and the lengths of the pages being crosswise of the webs; means for slitting the main webs along the central margin between the ends 70 of the pages; means adapted to effect a single quarter-turn of the main web-members perfected on one half the length of the main plate cylinders, to run on one side of the supplement cutter and carrier cylinders, 75 after making the quarter-turn, and adapted to effect a quarter-turn of other main web-members perfected on the other half the length of the main plate cylinders, to run on the other side of the supplement cutter and carrier 80 cylinders, after making the quarter-turn, and adapted to effect a single quarter-turn of the supplement web to run between the groups of quarter-turned and alined main web-members; means for leading the quarter turned supplement web-member to the supplement cutter and carrier cylinders; right and left and opposite main carrier cylinders positioned to coöperate with said supplement cutter and carrier 85 cylinders; means for disposing on one main carrier cylinder some main web-members from one group of quarter-turned main web-members; means for disposing on the other main carrier cylinder web-members from both groups of quarter-turned main web-members; stripping devices and leading devices adapted to strip supplement sheets from the supplement cutter and carrier cylinders and lead them between two main web-members one of which has been printed on one half the length of the main plate cylinders and the other has been printed on the other half the length of the main plate cylinders; main cutters coöperating with said main carrier cylinders respectively to cut into two-leaf sheets in length equal to the width of two pages plus margins, the main web-members running on said main carrier cylinders respectively; first-folders coöperating with said main carrier cylinders respectively to fold said two-leaf sheets along the central margin; means for assembling the first-folded sections; and a second-folder adapted to fold together the first-folded sections.
44. In an apparatus of the class described the combination of a first main printing unit comprising plate cylinders equipped with main plates extending around each plate cylinder a distance equal to the width of two pages plus margins and extending lengthwise of each plate cylinder a distance equal to the length of two pages plus margins and having columns lengthwise of the plate cylinders, and impression cylinders coöperating with said plate cylinders to perfect on both sides of a continuously moving web the matter of main pages in 100 rows, said pages being end-to-end with re- 105
- 110
- 115
- 120
- 125
- 130

- spect to each other and the lengths of the pages being crosswise of the web; a second printing unit adapted to perfect simultaneously a main web in width equal to the 5 length of one page plus margins and a supplement web in width equal to the length of one page plus margins and running edge-to-edge with respect to said main web, said second printing unit having plate cylinders 10 equipped with plates extending around the plate cylinders a distance equal to the width of two pages plus margins, and extending lengthwise of each plate cylinder a distance equal to the length of two pages plus margins, 15 and comprising four pages supplement-plate area and four pages main-plate area, and impression cylinders coöperating with said plate cylinders to perfect on both sides of a supplement web in width equal 20 to the length of one page plus margins, the matter of supplement pages with columns crosswise of the web and to perfect on a main web in width equal to the length of one page plus margins the matter of main 25 pages with columns crosswise of the web, the pages perfected on said supplement web being end-to-end with respect to the pages perfected on said main web; means for slitting the main web perfected by said first 30 main printing unit, along the central margin between the ends of the pages; means adapted to effect a quarter-turn of the web-members perfected by said first main printing unit to dispose one main web-member 35 on one side of the supplement cutter and carrier cylinders, after making the quarter-turn, and the other main web-member on the other side of the supplement cutter and carrier cylinders, after making the quarter- 40 turn, and adapted to effect a quarter-turn of the main web perfected by said second printing unit to dispose said main web on one side of said supplement cutter and carrier cylinders, after making the quarter- 45 turn, and adapted to effect a quarter-turn of said supplement web to dispose said supplement web in alinement with and between said quarter-turned main web-members; supplement cutter and carrier cylinders be- 50 tween the quarter-turned web-members perfected by said first printing unit; means for leading the quarter-turned supplement web to the supplement cutter and carrier cylinders; means for inserting one-leaf supplement sheets cut from the supplement web with two-leaf main sheets cut from the main webs; means for making the first fold; and a single second folder adapted to make the 55 second fold of all the papers with supple- 60 ments printed by both printing units.
45. The combination of web perfecting means two plates in circumference and two plates in width, and equipped with exclusively original plates having columns lengthwise of the plate cylinders and adapt- 65 ed to perfect on continuously moving webs the matter of two rows of pages on each side of each web; means for slitting the webs; means adapted to effect a quarter-turn of the perfected webs to aline face-to- 70 face in single alinement the rows of pages initially running edge-to-edge; a single-width cutter operable at half-speed to co-operate with one folder, or optionally operable at full-speed to coöperate with two 75 folders; a pair of single-width rotary folders; and sheet propelling means adapted to send alternate cuts at full-speed to two folders, or all the cuts at half-speed to one folder. 80
46. Printing means adapted to perfect on both sides of a continuously moving main web the matter of two rows of main pages and to perfect on each side of a supplement web the matter of supplement pages in a 85 row; means for slitting the main web into two web-members edge-to-edge; means for turning the main web-members to dispose them in single alinement face-to-face; cutter mechanism between the turned face-to-face main web-members; two folder mechanisms positioned to coöperate with said cutter mechanism; means for leading the supplement web to said cutter mechanism; and means for inserting cut sheets alter- 90 nately next to the face of web-members running to two folders respectively, or optionally inserting cut sheets in succession between the same web-members running to one folder mechanism. 95
47. The combination of main plate cylinders in width equal to the length of two pages plus margins and equipped with exclusively original plates extending around each plate cylinder a distance equal to the width of two 100 pages plus margins and having columns lengthwise of the plate cylinders; a supplement printing unit of four pages plate area in width equal to the length of one page plus margins and comprising on one plate 105 cylinder two plates of the same matter perfecting one side of the web, and comprising on the complementary plate-cylinder two plates of matter similar to each other but different from the matter of the plates of said first named plate-cylinder, and adapted to perfect the opposite side of the same web; means for slitting the main web along the central margin between the ends of the 110 pages to divide it into web-members edge-to-edge and in width equal to the length of one page plus margins; means for turning the main web-members to dispose face-to-face in parallel the web-members initially running edge-to-edge; a supplement cutter mecha- 115 nism between the turned main web-members perfected on one half the length of the main printing couples and the turned web-members perfected on the other half the length of the main printing couples; means for 120 125 130

turning and leading the supplement web to the supplement cutter mechanism with its edges parallel to the edges of the main web-members on both sides of the supplement 5 cutter mechanism; means for leading one turned main web-member on one side of the supplement cutter mechanism and the other turned member of the same web on the opposite side of the supplement cutter mechanism; means for associating the main web-members and cutting them into two leaf sheets; means for inserting successive one leaf sheets between the associated main web-members; and single width first folder mechanism adapted to fold together the two leaf main sheets with a one leaf insert-sheet between them.

48. In an apparatus of the class described, the combination of printing means a plurality of pages in width and adapted to perfect a plurality of main webs and a supplement web; web-turning means adapted to turn all the webs to aline in single alinement all the pages comprised in the entire 20 product of the printing means; means for leading the main webs divergently; means for leading the supplement web between the diverged main webs; single-width folder mechanism in position to fold sheets derived from the alined and turned main webs and supplement web; a single-width cutter mechanism between the web-turning means and the folder mechanism and adapted to cut the supplemental web into sheets; and sheet-propelling means adapted to propel all the cuts to the folder mechanism.

49. The combination of two opposite single-width folder devices and main cutter cooperating therewith; single-width cutter mechanism central with respect to said folder devices and invariably located between single-width main webs, or web-members, running to said folder devices and operable at full speed, or optionally at half speed; means for leading a supplement web, or web-member, invariably between the main webs, or web-members, to the central cutter mechanism likewise, invariably situated between the main webs, or web-members; sheet-propelling means adapted to propel sheets from the central cutter mechanism, alternately at full-speed to both folder devices and main cutters, or optionally to propel sheets at half-speed to one folder device 55 and one main cutter, with main webs, or main web-members, invariably on both sides of the central cutter mechanism, and with the sheets cut by said central cutter mechanism in position to fold between two main sheets derived from webs, or web-members, running from opposite sides of the central cutter mechanism.

50. In an apparatus of the class described, the combination of printing means a plurality of pages in width and adapted to

perfect a plurality of main webs and a supplement web; web-turning means adapted to turn all the webs to aline in single alinement all the pages comprised in the entire 70 product of the printing means; means for leading the main webs divergently; means for leading the supplement web between the diverged main webs; two single-width folder mechanisms in position to fold sheets derived from the turned and alined main webs and supplement web; a single-width cutter central with respect to the folder mechanisms and adapted to cut the supplement web into sheets; and sheet-propelling means adapted to propel cut sheets alternately to both folder mechanisms.

51. In an apparatus of the class described, the combination of printing means a plurality of pages in width and adapted to perfect a plurality of main webs and a supplement web; web-turning means adapted to turn all the webs to aline in single alinement all the pages comprised in the entire 85 product of the printing means; means for leading the main webs divergently; means for leading the supplement web between the diverged main webs; two single-width folder mechanisms in position to fold sheets derived from the turned and alined main webs and supplement web; a single-width cutter, central with respect to the folder mechanisms and adapted to cut the supplement web into sheets; and sheet-propelling means adapted to propel all the cut sheets to one folder mechanism, or optionally, to 90 propel cut sheets alternately to both folder mechanisms.

52. In an apparatus of the class described, the combination of printing means a plurality of pages in width and adapted to perfect a plurality of main webs and a supplement web; web-turning means adapted to turn all the webs to aline in single alinement all the pages comprised in the entire 105 product of the printing means; means for leading the main webs divergently; means for leading the supplement web between the diverged main webs; two single-width rotary folder mechanisms in position to fold sheets derived from the alined and turned main webs and supplement web; a single-width cutter central with respect to the folder mechanism and rotating at the same surface speed as the folder mechanisms and adapted to cut the supplement web into 110 sheets; and sheet-propelling means adapted to propel cut sheets alternately to both folder mechanisms.

53. In an apparatus of the class described, the combination of printing means a plurality of pages in width and adapted to perfect a plurality of main webs and a supplement web; web-turning means adapted to turn all the webs to aline in single alinement all the pages comprised in the entire 125

- product of the printing means; means for leading the main webs divergently; means for leading the supplement web between the diverged main webs; two single-width 5 rotary folder mechanisms in position to fold sheets derived from the turned and alined main webs and supplement web; a single-width cutter mechanism, central with respect to the folder mechanisms and rotating at a surface speed different from the surface speed of the folder mechanisms and adapted to cut the supplement web into sheets; and sheet-propelling means adapted to propel all the cuts to one folder mechanism.
54. In an apparatus of the class described, the combination of printing means a plurality of pages in width and adapted to perfect a plurality of main webs and a supplement web; web-turning means adapted to turn all the webs to aline in single alinement all the pages comprised in the entire product of the printing means; means for leading the main webs divergently; means 20 for leading the supplement web between the diverged main webs; two single-width rotary folder mechanisms in position to fold sheets derived from the turned and alined main webs and supplement web; a single-width cutter, central with respect to the folder mechanism and rotating at the same surface speed as the folder mechanisms, or optionally, at half-speed and adapted to cut the supplement web into sheets; and sheet-propelling means adapted to propel cut sheets alternately at full-speed to both folder mechanisms or optionally to propel all the cut sheets at half speed to one folder mechanism.
55. In an apparatus of the class described, the combination of printing means a plurality of pages in width and adapted to perfect a plurality of main webs and a supplement web; web-turning means adapted 45 to turn all the webs to aline in single alinement all the pages comprised in the entire product of the printing means; means for leading the main webs divergently; means for leading the supplement web between the 50 diverged main webs; two single-width rotary folder mechanisms in position to fold sheets derived from the turned and alined main webs and supplement web; a single-width cutter mechanism central with respect to the folder mechanisms and rotating at half-speed and adapted to cut the supplement web into sheets; and sheet-propelling means adapted to propel all the cuts to one folder mechanism.
56. In an apparatus of the class described, the combination of two full-speed main plate cylinders two pages in circumference and a plurality of pages in width and equipped with plates having columns 65 lengthwise of the plate cylinders and adapt-
- ed to print both sides of a continuously moving main web; means for forwarding the main web and slitting it to form web-members in width equal to the length of one page plus margins; two turners in line 70 with the main web-members and adapted to give each web-member one quarter turn to dispose them face to face; two secondary plate cylinders two pages in circumference and equipped with plates having columns 75 lengthwise of the plate cylinders and adapted to print one side of a supplement web by means of two plates on one secondary plate cylinder and print the reverse side of the supplement web by means of two 80 plates on the other secondary plate cylinder; means for forwarding the supplement web; means for disposing the quarter-turned supplement web between the two turners; half-speed supplement cutting 85 cylinders below said turners and adapted to cut the supplement web into sheets in length equal to the width of one page plus margins; a full-speed main cutter and a full-speed rotary first-folder in operative 90 relation to the supplement cutting cylinders and adapted to cut the main web-members into sheets in length equal to the width of two pages plus margins and fold the sheets along the central margin between the pages 95 including a supplement sheet in each paper; and a second folder adapted to make the second fold of the first-folded sheets to produce one complete second-folded paper including a supplement, said one complete 100 paper being printed, cut and folded at each revolution of the plate cylinders and all the main pages of said paper being printed by a single set of main plates and the two page supplement sheet being printed by two supplement plates and being inserted between two main sheets.
57. A single-width supplement cutter located between two face-to-face members of one full-speed main web and operable at 110 half-speed to cut from a single-width supplement web one-leaf supplement sheets for successive insertion with two-leaf main sheets derived from both web-members running to one folder, or optionally, operative 115 at full-speed to cut one-leaf supplement sheets for alternate insertion with two-leaf main sheets derived from the web-members respectively running to two folders.
58. A single-width supplement cutter located between two face-to-face members of one full-speed main web and operable at half-speed to cut from a single-width supplement web one-leaf supplement sheets for successive insertion with two-leaf main 120 sheets derived from either web-member and running to one folder, or for successive insertion between two web-members associated and running to one folder; or optionally operative at full-speed to cut one-leaf 125
- 65 lengthwise of the plate cylinders and adapt-
- 130

supplement sheets for alternate insertion with two-leaf sheets derived from the main web-members respectively and running to two folders.

- 5 59. A single-width supplement cutter located between two face-to-face members of one full-speed main web and operable at half-speed to cut from a single-width supplement web one-leaf supplement sheets for successive insertion with two-leaf main sheets derived from one web-member, or optionally operative at full-speed to cut one-leaf supplement sheets for alternate insertion with two-leaf main sheets derived from the main web-members respectively; in combination with two single-width first folders adapted to fold centrally two-leaf sheets derived from the respective main web-members; means for assembling the first-folded two-leaf sheets; and a second folder adapted to fold the assembled sheets together in the second fold.

60. A single-width supplement cutter located between two face-to-face members of one full-speed main web and operable at half-speed to cut from a single-width supplement web one-leaf supplement sheets for successive insertion with two-leaf main sheets derived from either main web-member and running to one folder, or for successive insertion between the two main web-members associated and running to one folder, or optionally operative at full-speed to cut one-leaf supplement sheets for alternate insertion with two-leaf main sheets derived from the main web-members respectively and running to two folders; in combination with two first folders operable concurrently to fold two-leaf main sheets derived from the respective main web-members or, operative singly to fold two-leaf main sheets derived from the associated main web-members; and two second folders adapted to coöperate with the first folders respectively, and each second folder likewise adapted to coöperate with the first folders jointly.

61. A rotary supplement printing unit comprising plate cylinders having printing surface, two plates in circumference and in width equal to the length of one page plus margins and having four pages supplement-plate-area with columns lengthwise of the plate cylinders, two plates being on one supplement plate cylinder and two plates being on the complementary supplement plate cylinder; in combination with means for turning the supplement web and leading it to a single-width supplement cutter between face-to-face single-width groups of main web-members; a single-width half-speed supplement cutter between two face-to-face groups of main web-members and rotating at the same surface speed as the supplement plate cylinders and adapted to make one cut

for each half revolution of the supplement printing cylinders and equipped with sheet-holding devices; means for stripping the cuts from the supplement cutter and leading them in succession in one direction; a plurality of main printing units comprising plate cylinders two plates in circumference and in width equal to the length of a plurality of pages plus margins and having exclusively original plates with columns lengthwise of the plate cylinders and adapted to perfect on a plurality of main webs the matter of main pages in rows; means for associating the webs, slitting them lengthwise to separate the rows of pages and turning the web-members to dispose all the rows of pages in two single-width face-to-face groups, one on each side of the supplement cutter; means for associating the two groups of main web-members in one composite group and leading the composite group to a single-width main cutter; a full-speed single-width main cutter operating on the composite group of main web-members and adapted to make one cut for each revolution of the main plate cylinders to cut the composite group, comprising the entire product of the main plate cylinders, into two-leaf main sheets; means for inserting one-leaf supplement sheets in succession between main web-members of two groups running from opposite sides of the supplement cutter in position to be folded with two-leaf main sheets cut by said main cutter; and a first folder adapted to fold said two-leaf sheets, including a one-leaf supplement sheet in each paper, to produce book-form papers including supplements and comprising a main page for every plate on the main plate cylinders.

62. A rotary supplement printing unit comprising plate cylinders having printing surface, two plates in circumference and in width equal to the length of one page plus margins and having four pages supplement-plate-area with columns lengthwise of the plate cylinders, two plates being on one supplement plate cylinder and two plates being on the complementary supplement plate cylinder; in combination with means for turning the supplement web and leading it to a single-width supplement cutter between face-to-face single-width groups of main web-members; a single-width half-speed supplement cutter between two face-to-face groups of main web-members and rotating at the same surface speed as the supplement plate cylinders and adapted to make one cut for each half-revolution of the supplement printing cylinders and equipped with sheet-holding devices; means for stripping the cuts from the supplement cutter and leading them in succession in one direction; a plurality of main printing units comprising plate cylinders two plates in circumference

- and in width equal to the length of a plurality of pages plus margins and equipped with exclusively original plates having columns lengthwise of the plate cylinders and 5 adapted to perfect on a plurality of main webs the matter of main pages in rows; means for associating the webs, slitting them lengthwise to separate the rows and turning the web-members to dispose all the 10 rows of pages in two single-width face-to-face groups, one on each side of the supplement cutter; means for associating the two groups of main web-members in one composite group and leading the composite 15 group to a single-width main cutter; a single-width main cutter operating on the composite group of main web-members and adapted to make one cut for each revolution of the main plate cylinders to cut the composite 20 group, comprising the entire product of the main plate cylinders, into two-leaf main sheets; means for inserting one-leaf supplement sheets in succession between main web-members of two groups running 25 from opposite sides of the supplement cutter in position to be folded with two-leaf main sheets cut by said main cutter; a first-folder adapted to fold the two-leaf sheets along the central margin between the pages; 30 and a second folder adapted to fold the first-folded sheets transversely of the first fold to produce a second-folded book-form paper including supplement and comprising an original main page for every plate on the 35 main plate cylinders.
63. A rotary supplement printing unit comprising plate cylinders having printing surface, two plates in circumference and in width equal to the length of one page plus 40 margins and having four pages supplement plate area with columns lengthwise of the plate cylinders, two plates being on one supplement plate cylinder and two plates being on the complementary supplement plate cylinder; in combination with 45 means for turning the supplement web and leading it to a supplement cutter between two single-width face-to-face groups of main web-members; a single-width half-speed supplement cutter between 50 two face-to-face groups of single-width main web-members and rotating at the same surface speed as the supplement plate cylinders and adapted to make one cut for each half-revolution of the supplement printing 55 cylinders and equipped with sheet-holding devices; means for stripping the successive sheets from the supplement cutter and leading them away from the supplement cutter in one direction; a plurality of main printing units equipped with cylinders two plates in circumference and in width equal to the 60 length of a plurality of pages plus margins and having columns lengthwise of the plate cylinders and adapted to perfect on a plurality of main webs the matter of main pages 65
- in rows; means for associating the webs, slitting them lengthwise to separate the rows of pages, turning the web-members and associating the rows of pages in two single-width groups one on each side of the supplement cutter and leading the respective groups to two single-width main cutters one on each side of the supplement cutter; 70 75 80 85 90 95 100 105 110 115 120 125 130
64. A rotary supplement printing unit comprising plate cylinders having printing surface, two plates in circumference and in width equal to the length of one page plus margins and having four pages supplement plate area with columns lengthwise of the plate cylinders, two plates being on one supplement plate cylinder and two plates being on the complementary supplement plate cylinder; in combination with means for turning the supplement web and leading it to a supplement cutter between two single-width face-to-face groups of main web-members; a single-width half-speed supplement cutter between two face-to-face groups of main web-members and rotating at the same surface speed as the supplement plate cylinders and adapted to make one cut for each half-revolution of the supplement printing cylinders and equipped with sheet-holding devices; means for stripping successive sheets from the supplement cutter; leaders adapted to lead the successive sheets away from the supplement cutter in one direction; a plurality of main printing units two plates in circumference and in width equal to the length of a plurality of pages plus margins and having columns lengthwise of the plate cylinders and adapted to perfect on a plurality of main webs the matter of main pages in rows; means for associating the webs, slitting them lengthwise to separate the rows of pages, turning the web-members and associating the rows of pages in two single-width groups one on each side of the supplement cutter and leading the respective groups to two single-width main cutters one on each side of the supplement cutter; 130

two single-width main cutters one on each side of the supplement cutter, and operating on the respective groups of main web-members and adapted to make one cut for each revolution of the main printing units to cut from each group two-leaf main sheets; two single-width first-folders adapted to fold centrally the two-leaf sheets cut by the main cutters respectively, to form first-folded sections; means for inserting successive one-leaf sheets running from the supplement cutter in position to be folded in the first-folded section folded by one first-folder; means for assembling the first-folded sections; and one second-folder adapted to fold the sections together in the second fold to produce second-folded papers in sections including a supplement in one section said second-folded papers comprising the entire product of the main printing units.

65. A rotary supplement printing unit comprising plate cylinders having printing surface, two plates in circumference and in width equal to the length of one page plus margins and having four pages supplement plate area with columns lengthwise of the plate cylinders, two plates being on one supplement plate cylinder and two plates being on the complementary supplement plate cylinder; in combination with means for leading the supplement web to a supplement cutter-unit; a two-cylinder supplement cutter-unit rotating at the same surface speed as the supplement plate cylinders and adapted to make one cut for each half-revolution of the supplement printing cylinders and equipped with sheet-holding devices adapted to hold each successive sheet on one cylinder during partial rotation of that cylinder, after making the cut; means for stripping the successive sheets from said cylinder; leaders adapted to lead the successive sheets away from said cylinder; a plurality of main printing units equipped with plate cylinders two plates in circumference, a plurality of plates in width and having columns lengthwise of the plate cylinders and adapted to perfect on a plurality of main webs the matter of main pages in rows; means for associating the main webs, slitting them lengthwise to separate the rows of pages, turning the web-members and associating the rows of pages in two single-width groups, one on each side of the supplement cutter-unit; means for associating in one composite group the two single-width groups running from opposite sides of the supplement cutter-unit and inserting between the associated groups half-speed supplement sheets led by said leaders, in position to be folded with two-leaf main sheets cut from said composite group; a single-width main cutter making one cut for each revolution of the main plate cylinders and adapted to cut into two-leaf main sheets the composite group of main web-members comprising the entire product of the main plate cylinders equipped with a full complement of exclusively original plates for main pages with a supplement sheet inserted with each paper; and a single-width first folder adapted to fold said two-leaf sheets including a supplement derived from a supplement web situated between two main web-members running from opposite sides of the supplement cutter.

leaf sheets led by said leaders into position to be folded with the two-leaf main sheets folded by one folder; and second folders co-operating with the first folders respectively to produce simultaneously two second-folded papers one with supplement and the other without supplement.

66. A rotary supplement printing unit comprising plate cylinders having printing surface, two plates in circumference and having four pages supplement plate area, two plates being on one supplement plate cylinder and two plates being on the complementary supplement plate cylinder; in combination with means for turning the supplement web and leading it to a supplement cutter-unit; a two-cylinder half-speed supplement cutter-unit rotating at the same surface speed as the supplement plate cylinders and adapted to make one cut for each half-revolution of the supplement printing cylinders and equipped with sheet-holding devices adapted to hold each successive sheet on one cylinder during partial rotation of that cylinder, after making the cut; means for stripping the successive sheets from said cylinder; leaders adapted to lead the successive sheets away from said cylinder; a plurality of main printing units equipped with plate cylinders two plates in circumference, a plurality of plates in width and having columns lengthwise of the plate cylinders and adapted to perfect on a plurality of main webs the matter of main pages in rows; means for associating the main webs, slitting them lengthwise to separate the rows of pages, turning the web-members and associating the rows of pages in two single-width groups, one on each side of the supplement cutter-unit; means for associating in one composite group the two single-width groups running from opposite sides of the supplement cutter-unit and inserting between the associated groups half-speed supplement sheets led by said leaders, in position to be folded with two-leaf main sheets cut from said composite group; a single-width main cutter making one cut for each revolution of the main plate cylinders and adapted to cut into two-leaf main sheets the composite group of main web-members comprising the entire product of the main plate cylinders equipped with a full complement of exclusively original plates for main pages with a supplement sheet inserted with each paper; and a single-width first folder adapted to fold said two-leaf sheets including a supplement derived from a supplement web situated between two main web-members running from opposite sides of the supplement cutter.

67. A rotary supplement printing unit comprising plate cylinders having printing surface, two plates in circumference and having four pages supplement plate area,

two plates being on one supplement plate cylinder and two plates being on the complementary supplement plate cylinder; in combination with means for leading the supplement web to a supplement cutter-unit; a two-cylinder single-width supplement cutter-unit rotating independently of the folders and at the same surface speed as the supplement plate cylinders and adapted to make 5 one cut for each half-revolution of the supplement printing cylinders and equipped with sheet-holding devices adapted to hold each successive sheet on one cylinder during partial rotation of that cylinder, after 10 making the cut; means for stripping the successive sheets from said cylinders, and leaders adapted to lead the successive sheets away from said cylinders; a plurality of main printing units comprising plate cylinders two plates in circumference, and in width equal to the length of a plurality of plates and equipped with exclusively original plates having columns lengthwise of the plate cylinders and adapted to perfect 15 20 25 30 35 40 45 50 55 60 65 70 75 80 85 90 95 100 105 110 115 120 125 130

of the supplement printing cylinders and equipped with sheet-holding devices adapted to hold alternate sheets on the cylinders respectively, during partial rotation of the respective cylinders, after making the cut; means for stripping the sheets from the cylinders respectively; leaders adapted to lead the sheets oppositely away from the cylinders respectively; a plurality of main printing units equipped with cylinders two plates in circumference, a plurality of plates in width and having columns lengthwise of the plate cylinders and adapted to perfect on a plurality of main webs the matter of main pages in rows; means for associating the webs, slitting them lengthwise to separate the rows of pages, turning the web-members and associating the rows of pages in two single-width groups, one on each side of the supplement cutter unit and leading the respective groups to two single-width main cutters, one on each side of the supplement cutter unit; two single-width main cutters operating on the respective groups of main web-members and adapted to make one cut for each revolution of the main printing units, to cut two-leaf sheets from each group; two single-width first-folders respectively adapted to fold centrally the two-leaf sheets cut by the main cutters; means for inserting one-leaf sheets led by said leaders in position to be folded with two-leaf sheets running to each first-folder; means for assembling the first-folded sections; and one second-folder adapted to fold the sections together in the second fold.

69. The combination of printing means two plates in circumference and adapted to perfect main webs and a supplement web; means for propelling the main webs to one single-width main cutter or to two opposite single-width main cutters; means for propelling the supplement web to a single-width supplement cutter; a single-width supplement cutter rotative independently of the folders, at the same surface speed as the rotary folder, or rotary folders, with which it co-operates, or at a different surface speed, and adapted to make one cut for each half-revolution of the supplement printing means, said supplement cutter comprising a first cutter cylinder equipped with sheet-holding devices and means for rendering the sheet-holding devices of said first cutter cylinder effective or ineffective and a second cutter cylinder equipped with sheet-holding devices and means for rendering the sheet-holding devices of said second cutter cylinder effective or ineffective; two rotary folders positioned to co-operate with the main cutters and with said supplement cutter; two single-width main cutters adapted to make one cut for each revolution of the main printing means to cut off two-leaf main sheets running to said folders respectively.

68. A rotary supplement printing unit comprising plate cylinders having printing surface, two plates in circumference and in width equal to the length of one page plus margins and having four pages supplement plate area, two plates being on one supplement plate cylinder and two plates being on the complementary supplement plate cylinder; in combination with means for leading the supplement web to a supplement cutter-unit; a two-cylinder single-width supplement cutter-unit rotating independently of the folders and at the same surface speed as the supplement plate cylinders and adapted to make one cut for each half-revolution

5 tively; and sheet-propelling means adapted to propel one-leaf supplement sheets to one folder in position to be inserted with two-leaf main sheets cut by one main cutter when the sheet-holding means of one supplement cutter cylinder are effective and adapted to propel supplement sheets alternately to two folders in position to be inserted with two-leaf main sheets cut by the 10 main cutters when some sheet-holding means of both supplement cutter cylinders are effective.

15 70. The combination of means for propelling a single-width supplement web to a single-width cutter mechanism between two main webs; a single-width supplement cutter rotative at the same surface speed as the rotary folder, or rotary folders with which it cooperates, or at a different surface speed, 20 and adapted to make one cut for each half-revolution of the supplement printing means, said supplement cutter comprising a first cutter cylinder equipped with sheet-holding devices and means for rendering the 25 sheet-holding devices of said first cutter cylinder effective or ineffective and a second cutter cylinder equipped with sheet-holding devices and means for rendering the sheet-holding devices of said second cutter cylinder effective or ineffective; two opposite rotary folders positioned to coöperate with said supplement cutter mechanism; main cutters adapted to make one cut for each revolution of the main web-perfeting means to cut off 30 two-leaf main sheets running to said folders respectively; and sheet-propelling means adapted to propel supplement sheets to one folder in position to be inserted with two-leaf sheets cut by one main cutter when the 35 sheet-holding means of one supplement cutter cylinder are effective and adapted to propel supplement sheets alternately to two folders in position to be inserted with two-leaf sheets cut by two main cutters when the 40 sheet-holding means of both supplement cutter cylinders are effective.

45 71. The combination of a single-width first cutter cylinder equipped with sheet-holding devices; and means for rendering said sheet-holding devices effective or ineffective; a single-width second cutter cylinder equipped with sheet-holding devices and means for rendering said sheet-holding devices effective or ineffective; means for rotating said first and second cutter cylinders at changeable speeds; and sheet-propelling means adapted to propel all the cuts in one direction when the sheet-holding devices of one cutter cylinder only are in use and 50 adapted to propel cuts alternately in opposite directions when some sheet-holding devices of both cutter cylinders are effective.

55 72. A two-cylinder single-width cutter adapted to rotate at full-speed or optionally 60 at half-speed and adapted to make one cut

75 for each half-revolution of the plate cylinders and equipped with sheet-holding devices effective to hold all the cuts on one cylinder during the partial rotation of that cylinder immediately after the cut, or optionally effective to hold on the respective cylinders sheets running alternately to two folders during the partial rotation of both cylinders immediately after the cut, and means 80 adapted to strip the sheets from the respective cylinders; in combination with two single-width folders operable jointly to fold all the sheets cut off by the cutter operating at full-speed, or optionally, either one operative singly to fold all the cuts cut off by the cutter operating at half-speed.

85 73. The combination of printing couples comprising plate cylinders in width equal to the length of two pages plus margins and in circumference equal to the width of two pages plus margins and equipped with exclusively original plates and including supplement-plate area of four plates, two supplement plates being on one supplement-plate cylinder and two supplement-plates 90 being on the complementary supplemental-plate cylinder; a single-width supplement cutter positioned to cut into sheets in length equal to the width of one page plus margins the supplement web perfected by the supplement printing couples; means for slitting the main webs; means for leading on one side of the supplement cutter the main web-members printed on one-half the length of the main plate cylinders and leading on the 95 other side of the supplement cutter the main web-members printed on the other half the length of the main plate cylinders; two single-width main cutters adapted to cut off at one cut for each revolution of the printing 100 couples, the entire page-for-plate product of the main printing couples; means for inserting supplement sheets cut by the supplement cutter with the main web-members running to one main cutter; and two first-folders adapted to fold the sheets cut by the 105 main cutters respectively.

110 74. The combination of printing couples comprising plate cylinders in width equal to the length of two pages plus margins and in circumference equal to the width of two pages plus margins and equipped with exclusively original plates and including supplement-plate area of four plates, two supplement plates being on one supplement-plate cylinder and two supplement plates 115 being on the complementary supplemental-plate cylinder; a single-width supplement cutter positioned to cut into sheets in length equal to the width of one page plus margins the supplement web perfected by the supplement printing couples; means for slitting the main webs; means for leading on one side of the supplement cutter the main web-members printed on one-half the length of 120 the supplement printing couples; means for inserting supplement sheets cut by the supplement cutter with the main web-members running to one main cutter; and two first-folders adapted to fold the sheets cut by the 125 main cutters respectively.

125 75. A two-cylinder single-width cutter adapted to rotate at full-speed or optionally at half-speed and adapted to make one cut

the main plate cylinders and leading on the other side of the supplement cutter the main web-members printed on the other half the length of the main plate cylinders; means for associating in one single-width group all the main web-members running on both sides of the supplement cutter; means for inserting successive supplement sheets cut by the supplement cutter, between face-to-face main web-members running to the main cutter; a single-width main cutter adapted to cut off at one cut for each revolution of the main printing couples, the entire product of the main printing couples; and one folder adapted to make the first fold of sheets cut by said main cutter.

75. The combination of printing couples comprising plate cylinders in width equal to the length of two pages plus margins and in circumference equal to the width of two pages plus margins and equipped with exclusively original plates for main pages and including supplement-plate area of four plates, two supplement plates being on one supplement-plate cylinder and two supplement plates being on the complementary supplement-plate cylinder; a single-width supplement cutter positioned to cut into sheets in length equal to the width of one page plus margins the supplement web, or web-member, perfected by the supplement printing couples; means for slitting the main webs; means for leading on one side of the supplement cutter the main web-members printed on one-half the length of the main plate cylinders and leading on the other side of the supplement cutter the main web-members printed on the other half the length of the main plate cylinders; means for associating in one single-width group all the main web-members running on both sides of the supplement cutter; means for inserting successive supplement sheets cut by the supplement cutter between face-to-face main web-members running to the main cutter; a single-width main cutter adapted to cut off at one cut for each revolution of the main printing couples the entire product of the main printing couples; one first-folder adapted to make the first fold of sheets cut by said main cutter; and a second folder adapted to make the second fold of papers first-folded by said first folder.

76. The combination of printing couples comprising plate cylinders in width equal to the length of two pages plus margins and in circumference equal to the width of two pages plus margins and equipped with exclusively original plates and including supplement-plate area of four plates, two supplement plates being on one supplement-plate cylinder and two supplement plates being on the complementary supplement-plate cylinder; a single-width supplement cutter positioned to cut into sheets in length equal

to the width of one page plus margins the supplement web perfected by the supplement printing couples; means for slitting the main webs; means for leading on one side of the supplement cutter the main web-members printed on one-half the length of the main plate cylinders and leading on the other side of the supplement cutter the main web-members printed on the other half the length of the main plate cylinders; two single-width main cutters adapted to cut off at one cut for each revolution of the printing couples, the entire page-for-plate product of the main printing couples; and means for inserting supplement sheets cut by the supplement cutter with the main web-members running to one main cutter.

77. The combination of printing couples comprising plate cylinders in width equal to the length of two pages plus margins and in circumference equal to the width of two pages plus margins and equipped with exclusively original plates and including supplement-plate area of four plates, two supplement plates being on one supplement plate cylinder and two supplement plates being on the complementary supplement-plate cylinder; a single-width supplement cutter positioned to cut into sheets in length equal to the width of one page plus margins the supplement web perfected by the supplement printing couples; means for slitting the main webs; means for leading on one side of the supplement cutter the main web-members printed on one-half the length of the main plate cylinders and leading on the other side of the supplement cutter the main web-members printed on the other half the length of the main plate cylinders; means for inserting supplement sheets cut by the supplement cutter with the main web-members running to one main cutter; two single-width main cutters adapted to cut off at one cut for each revolution of the printing couples; two first-folders adapted to make the first fold of sections cut by the main cutters respectively; and one second folder adapted to fold together in the second fold the sections first-folded by said first folders.

78. The combination of main printing means comprising plate cylinders in width equal to the length of two pages plus margins and in circumference equal to the width of two pages plus margins and having columns lengthwise of the plate cylinders; supplement printing means two pages in circumference and in width equal to the length of one page plus margins and having a supplement printing area of four plates, two supplement plates of a kind being on one side of the supplement web, and perfecting supplement plates of a kind but different

- from the supplement plates on the first named supplement plate cylinder being on the complementary plate cylinder and perfecting the other side of the same supplement web; a single-width half-speed supplement cutter, adapted to make two cuts for each revolution of the supplement printing means, to cut the supplement web into sheets in length equal to the width of one page plus margins; means for slitting the main web into members in width equal to the length of one page plus margins; means for turning the main web-members, initially running edge-to-edge to dispose them face-to-face and with their edges parallel, one main web-member being on each side of the supplement cutter; means for turning the supplement web to align it with the main web-members; means for leading the supplement web to the supplement cutter between the face-to-face main web-members; means for associating the main web-members running from both sides of the supplement cutter; means for inserting successive half-speed supplement sheets cut by the supplement cutter, between face-to-face main web-members running to the main cutter; a single-width main cutter adapted to cut off, at one cut for each revolution of the main printing means the entire product of the main printing means printed by exclusively original plates for main pages the cut sheets being in length equal to the width of two pages plus margins; a first-folder adapted to fold centrally lengthwise along the margins between the pages the sheets cut by the main cutter; a second folder adapted to fold the first-folded sheets transversely to the crease of the first fold; and a delivery device adapted to deliver the second-folded papers including supplements.
79. The combination of a plurality of plate cylinders two pages in circumference, a plurality of pages in width and equipped with plates having columns lengthwise of the plate cylinders and adapted to print both sides of a plurality of continuously moving main webs; means for slitting the webs into web-members in width equal to the length of one page plus margins; means for disposing all the main web-members face to face in single alinement; two secondary plate cylinders two pages in circumference, equipped with plates having columns lengthwise of the plate cylinders and adapted to perfect one side of a supplement web by means of two plates lying around one plate cylinder and perfect the reverse side of the same web by two plates lying around the other plate cylinder; means for leading the supplement web between the aligned main web-members; two main cutters in line with the face to face web-members and adapted to cut them into sheets in length equal to the width of two pages plus margins; means for forwarding some web-members to one main cutter and other web-members to the other main cutter; two supplement cylinders equipped with means for carrying supplement sheets alternately on said cylinders to be inserted with main sheets cut by two main cutters; two rotary first-folders cooperating with the main cutters respectively to fold the main sheets centrally with a two-page insert sheet in each
80. The combination of a plurality of plate cylinders two pages in circumference, a plurality of pages in width and equipped with plates having columns lengthwise of the plate cylinders and adapted to print both sides of a plurality of continuously moving webs; means for slitting the webs into web-members in width equal to the length of one page plus margins; means for disposing all the web-members face to face in single alinement; two main cutters in line with the face to face web-members and adapted to cut the web-members into sheets in length equal to the width of two pages plus margins; means for forwarding some web-members to one main cutter and other web-members to the other main cutter; two rotary first-folders cooperating with the main cutters respectively; means for forwarding to one second-folder the sheets folded on one rotary first-folder and forwarded to the other second-folder the sheets folded on the other first-folder; and two second-folders cooperating with the first-folders respectively; to produce two complete second-folded book-form papers printed from a single set of plates for each paper and folded at each revolution of the plate cylinders.
81. The combination of a plurality of main plate cylinders two pages in circumference, a plurality of pages in width and equipped with plates having columns lengthwise of the plate cylinders and adapted to print both sides of a plurality of continuously moving main webs; means for slitting the webs into web-members in width equal to the length of one page plus margins; means for disposing all the main web-members face to face in single alinement; two secondary plate cylinders two pages in circumference, equipped with plates having columns lengthwise of the plate cylinders and adapted to perfect one side of a supplement web by means of two plates lying around one plate cylinder and perfect the reverse side of the same web by two plates lying around the other plate cylinder; means for leading the supplement web between the aligned main web-members; two main cutters in line with the face to face web-members and adapted to cut them into sheets in length equal to the width of two pages plus margins; means for forwarding some web-members to one main cutter and other web-members to the other main cutter; two supplement cylinders equipped with means for carrying supplement sheets alternately on said cylinders to be inserted with main sheets cut by two main cutters; two rotary first-folders cooperating with the main cutters respectively to fold the main sheets centrally with a two-page insert sheet in each

paper; means for forwarding the first-folded sheets from one first-folder to one second-folder and means for forwarding the first-folded sheets from the other first-folder to another second-folder; and two second-folders adapted to make the second fold of the first-folded sheets running from the first-folders respectively; to produce at each revolution of the plate cylinders two complete book-form papers, including a one-leaf two-page insert sheet in each paper, printed by a single set of plates for each paper.

82. The combination of a plurality of main plate cylinders two pages in circumference a plurality of pages in width, equipped with plates having columns lengthwise of the plate cylinders and adapted to print both sides of a plurality of continuously moving main webs; two secondary plate cylinders two pages in circumference equipped with plates having columns lengthwise of the plate cylinders and adapted to print one side of a secondary web by means of two plates lying around one plate cylinder and print the reverse side of the secondary web by means of two plates lying around the other plate cylinder; means for slitting the main webs into web-members in width equal to the length of one page plus margins; means for disposing all the main web-members face to face in single alinement; means for disposing the secondary web between the alined main web-members; two main cutters adapted to cut the main web-members into sheets in length equal to the width of two pages plus margins; means for forwarding some web-members to one main cutter and other web-members to the other main cutter; a secondary cutter intermediate of the main cutters and adapted to cut the secondary web into sheets in length equal to the width of one page plus margins; means for operating the secondary cutter at half the surface speed of the rotary folders; means for forwarding the half-speed secondary sheets and inserting them with the main sheets cut by one main cutter; two rotary first-folders adapted to fold centrally the sections cut by the main cutters respectively; means for forwarding the first-folded sections from both first-folders in a straight line to an assembling device; an assembling device adapted to assemble the first-folded sections running from both first-folders; means for forwarding the assembled sections to one second-folder; and one second-folder adapted to make the second fold of the assembled first-folded sections; to produce at each revolution of the plate cylinders one complete paper folded in sections, one section having an insert sheet, all the main pages of said paper being printed by a single set of plates and the insert sheet being printed by two plates.

83. The combination of a plurality of main plate cylinders two pages in circumference equipped with plates having columns lengthwise of the plate cylinders and adapted to print a plurality of main webs; means for slitting the main webs and turning the web-members to dispose all the main web-members face to face in single alinement; a main cutter adapted to cut the main web-members into sheets in length equal to the width of two pages plus margins; a rotary first-folder and a second-folder in operative relation to the main plate cylinders; two secondary plate cylinders two pages in circumference equipped with plates having columns lengthwise of the plate cylinders and adapted to print one side of a secondary web by means of plates occupying a width of the plate cylinders equal to the length of one page plus margins and print the reverse side of the secondary web by means of similar plates on the other plate cylinder; two secondary cutter cylinders in line with the main cutter and the rotary folder and adapted to rotate at full-speed or half-speed; means for forwarding the secondary web to the secondary cutter cylinders; means for forwarding the main web-members to the main cutter; means for rotating the secondary cutter cylinders at half-speed to forward all the secondary cuts to be inserted with the main sheets running to the rotary folder; means for rotating the secondary cutter cylinders at the same surface speed as the main cutter to carry secondary cuts alternately from the secondary cutter cylinders; a delivery device positioned to coöperate with the secondary cutter cylinders; means for forwarding from one secondary cutter cylinder to the rotary folder cuts running from one half-circumference of the secondary plate cylinders and forwarding to the delivery device cuts running from the other half-circumference of the secondary plate cylinders.

84. The combination of a plurality of plate cylinders two pages in circumference and equipped with plates having columns lengthwise of the plate cylinders; a supplement cutter device; two main cutting devices, two rotary folders; an assembling device and two second folders all in operative relation to the plate cylinders; and means for operating the supplement cutting device at the same surface speed as the main cutters and rotary folders, or at half the surface speed of the main cutters and rotary folders.

85. The combination of two co-acting rotative cutter cylinders; means for rotating said cutter cylinders at either one of two different speeds; sheet-holding means on both cylinders; controlling means controlling the sheet-holding means, to cause all the cuts to run at the slower speed, all in

one direction from either cutter cylinder or optionally to cause the cuts to run at either speed alternately in different directions from the cutter cylinders, the cuts from one cutter cylinder running in one direction and the cuts from the other cutter cylinder running in a different direction; means for stripping the cuts from the cutter cylinders and means for propelling the cuts away from the cutter cylinders.

86. The combination of a secondary cutter adapted to cut short sheets; two opposite rotary folders; two main cutting devices coöperating with the rotary folders respectively; an assembling device in line with the rotary folders; two second-folder devices coöperative with said assembling device; means for operating the secondary cutter at the same surface speed as the main cutting devices or at half the surface speed of the main cutting devices; means for forwarding short sheets alternately from said secondary cutter to two opposite rotary folders running at the same surface speed as the main cutting devices; means for inserting short sheets on the inside of long sheets cut by the main cutting devices to be folded by the rotary folder, or rotary folders, as the case may be; means for forwarding the first-folded sections, or first-folded papers, as the case may be, running in a straight line with their folded edges in the lead to the assembling device; two second-folders positioned to coöperate with the assembling device; and forwarding devices adapted to forward all the assembled sections to one second-folder and also effective to forward two book-form papers to two second-folders respectively.

87. The combination of plate cylinders a plurality of pages in width, two pages in circumference and equipped with plates having columns lengthwise of the plate cylinders and adapted to print both sides of a main web of a width equal to the length of two pages plus margins, and both sides of a supplement web of a width equal to the length of one page plus margins; means for slitting the main web to form single width web-members; two opposite turners positioned to effect a single quarter turn of the main web-members to dispose them in parallel face to face; and means for disposing the supplement web between said turners and in parallel with the quarter-turned main web-members.

88. The combination of plate cylinders a plurality of pages in width, two pages in circumference and equipped with plates having columns lengthwise of the plate cylinders and adapted to print both sides of

a main web of a width equal to the length of two pages plus margins, and both sides of a supplement web of a width equal to the length of one page plus margins; means for slitting the main web to form single width web-members; two opposite turners positioned to effect a single quarter-turn of the main web-members to dispose them in parallel face to face; means for disposing the supplement web between said turners and in parallel with the quarter-turned main web-members; and a cutter beyond the turners as the webs run and making two cuts at each revolution of the plate cylinders to cut the supplement web into sheets in length equal to the width of one page plus margins.

89. In combination with a single-ender printing machine; a single-width half-speed supplement cutter, a single-width full-speed main cutter, a full speed single width rotary first folder, a second folder and a delivery device at right angles to the rotary first folder, all at one end of the printing machine; means for forwarding a half-speed supplement web to the supplement cutter; means for forwarding one main web on one side of the supplement cutter to the main cutter and forwarding another main web on the other side of the supplement cutter to the main cutter; sheet-holding means adapted to take and hold the leading ends of the main webs and the leading end of the supplement sheet to lead them downwardly; and means for leading the supplement web into position to be guided between the downwardly running main webs before cutting off the supplement sheet.

90. In a multiple-deck apparatus the combination of printing means comprising full-speed plate-cylinders in circumference equal to the width of two pages plus margins, and equipped with plates having columns parallel to the axes of the plate-cylinders and adapted to print both sides of two main webs, and half-speed plate-cylinders in circumference equal to the width of two pages plus margins and equipped with plates having columns parallel to the axes of the plate cylinders and adapted to print both sides of a supplement web; means for forwarding the perfected main webs and the perfected supplement web in parallel single-width alignment; a half-speed single-width supplement cutter on a higher level than the means completing the first fold and adapted to cut the supplement web into sheets in length equal to the width of one page plus margins; means for associating both main webs in position to be cut by one main cutter; a full speed single-width main cutter and rotary folder adapted to cut the associated main webs into main sheets in length equal to the width of two pages plus margins and fold said sheets along the central

- margin between the pages; means for forwarding the first-folded sheets running with their first-folded edges in the lead to a second folder; a second folder adapted to make the second fold at right-angles to the crease of the first fold; and a delivery device at right angles to the rotary first-folder and adapted to receive second-folded papers.
- 10 91. In a multiple-deck apparatus the combination of printing means comprising full-speed plate cylinders in circumference equal to the width of two pages plus margins, and equipped with plates having columns parallel to the axes of the plate cylinders and adapted to print both sides of two main webs, and half-speed plate cylinders in circumference equal to the width of two pages plus margins and equipped with plates having columns parallel to the axes of the plate cylinders and adapted to print both sides of a supplement web; means for forwarding the perfected main webs and the perfected supplement web in parallel single-width alignment with the half-speed supplement web between the main webs; a half-speed single-width supplement cutter on a higher level than the means completing the first fold and adapted to cut the supplement web into sheets in length equal to the width of one page plus margins; means for disposing the main webs, one on each side of the supplement cutter, and associating them in position to be cut by one main cutter; a full-speed single-width main cutter and a rotary folder adapted to cut the associated main webs into main sheets in length equal to the width of two pages plus margins and fold said main sheets along the central margin between the pages; a paster between the main webs in position to apply paste on one main web along the central margin between main pages; means for forwarding the leading end of the supplement web downwardly in position to be guided between the main webs before cutting off the supplement sheet; sheet holding means adapted to take and hold the leading ends of the associated main webs and the leading end of the supplement sheet before cutting off the main sheets; a second folder adapted to make the second fold of the first folded sheets, at right angles to the crease of the first fold, including one supplement sheet pasted in each paper; and a delivery device at right angles to the rotary first folder.
92. The combination of printing means comprising plate cylinders a plurality of pages in width, two pages in circumference, equipped with plates having columns lengthwise of the plate cylinders and adapted to print both sides of a plurality of plural-page-wide webs; web-forwarding means adapted to forward the associated webs; slitting means adapted to slit the associated webs into web-members in width equal to the length of one page plus margins; opposite turners beyond the slitting means as the webs run and adapted to effect a quarter turn of said web-members to dispose them in two opposite groups face to face; means for associating on a main cutter and rotary folder the opposite groups of quarter turned web-members; a main cutter and a rotary folder in line with the quarter turned web-members and adapted to cut the associated groups of web-members into sheets in length equal to the width of two pages plus margins and fold the sheets centrally along the margins between the pages; and a second folder at right angles to and in line with the first folder and adapted to make the second fold across the crease of the first-folded sheets, to fold as one product a complete paper printed by one set of plates and folded at each revolution of the plate cylinders.
93. The combination of web-forwarding means adapted to forward a plurality of associated plural-page-wide webs and a supplement web or web member in line with the main web-members on either side of the slitting means; means for slitting the associated plural-page-wide webs to form main web-members; turners beyond the slitting means as the webs run, and adapted to effect a quarter turn of the web-members to dispose them in two opposite groups face to face and to dispose the supplement web or web member in position to run to a supplement cutter in line with the opposite groups of main web members; half speed supplement cutting means between and in line with the opposite groups of web-members and adapted to cut the supplement web or web member into one-leaf sheets; a main cutter and rotary folder in line with both groups of web-members; means for forwarding one group of web-members on one side of the supplement cutter to the main cutter and rotary folder, and forwarding the other group of web-members on the other side of the supplement cutter to the same main cutter and rotary folder, in position for the main cutter to cut the associated groups of web-members into two-leaf main cuts; and means for inserting one supplement cut with each main cut.
94. The combination of web-forwarding and slitting means; two turners beyond the slitting means as the webs run and adapted to give the webs or web-members one quarter turn; two rotary half-speed supplement-cutting cylinders at right angles to the web-forwarding and slitting means; a main cutter and a rotary first-folder parallel to the supplement-cutting cylinders; and a second folder at right angles to said rotary first-folder and adapted to make the second fold across the crease of the first fold.

95. The combination of printing means comprising plate cylinders two pages in circumference a plurality of pages in width, equipped with plates having columns lengthwise of the plate cylinders and adapted to print both sides of a plurality of plural-page-wide webs; associating, forwarding and slitting means adapted to associate, forward and slit the webs to form web-members in width equal to the length of one page plus margins; turners beyond the web-forwarding and slitting means, as the webs run, and adapted to give the web members one quarter turn to dispose them face to face; supplement cutting means in line with the quarter-turned web members; a main cutter and a rotary first-folder in line with the quarter turned web members; means for forwarding the supplement web-members to the supplement-cutting means; means for forwarding the quarter turned and aligned main web-members to the main cutter and first-folder; a second folder positioned to coöperate with said rotary first-folder; a delivery device parallel to the rotary first-folder; another delivery device at right angles to the rotary first-folder; means for inserting one supplement cut with each main cut on the main cutter and first-folder; and means for forwarding every second supplement-cut to the delivery device parallel to the rotary folder, the mechanisms being in such relation to each other that the supplement cuts running from one half-circumference of the supplement-plate area of the plate cylinders go to the rotary folder and the cuts running from the other half-circumference of the supplement-plate area of the plate cylinders go to the delivery device parallel to the rotary folder; and means for forwarding the second folded sheets to the delivery device at right angles to the rotary first-folder; to produce complete papers including a two-page insert in each paper, said papers being printed by one set of plates and printed and folded at each revolution of the plate cylinders.

96. The combination of web-forwarding means adapted to forward main webs and a supplement web; a supplement cutter effective to cut the supplement web into one-leaf sheets; a main cutter and a rotary first-folder effective to cut the main webs into two-leaf sheets and fold the sheets; a second folder at right angles to the first-folder; primary delivery means at right angles to the first-folder; secondary delivery means parallel to the first-folder; means for inserting one supplement cut with each main cut going through the first and second folders to the primary delivery means; and means for forwarding every second supplement cut to the secondary delivery means.

97. The combination of full-speed plate cylinders effective to print both sides of a

plurality of webs a plurality of pages in width; means for slitting the webs to form main web-members and a supplement web-member; means for disposing all the web-members in single-width alinement; two single-width first-folders adapted to fold centrally main sheets in length equal to the width of two pages plus margins; two single-width main cutters adapted to cut main webs into sheets in length equal to the width of two pages plus margins; single-width supplement cutting means on a higher level than the rotary first-folders and adapted to cut the supplement web-member into sheets in length equal to the width of one page plus margins; means adapted to carry the supplement sheets downwardly and alternately to the rotary first-folders and insert them next to the inside of the main webs; two second-folders below said rotary first folders and adapted to make the second fold across the crease of the first fold; and means for forwarding the first folded sheets from the first folders to the second folders respectively.

98. The combination of full-speed plate cylinders effective to print both sides of a plurality of webs a plurality of pages in width; means for slitting the webs to form main web-members and a supplement web-member; means for disposing all the web-members in single width alinement; two opposite single-width rotary first-folders; two single-width main cutters coöperating with the rotary first-folders, respectively, and adapted to cut off sheets in length equal to the width of two pages plus margins; secondary cutting means on a higher level than said rotary first-folders and adapted to cut off sheets in length equal to the width of one page plus margins; and two second-folders at right angles to said rotary first-folders.

99. The combination of full-speed plate-cylinders effective to print both sides of a full-speed main web; half-speed plate cylinders effective to print both sides of a half-speed supplement web; means for slitting the main web and disposing the web-members in single-width alinement face to face, one of said web-members being on one side of the supplement cutter and the other web-member being on the other side of the supplement cutter; one single-width full-speed rotary first-folder adapted to fold main sheets centrally; a pair of single-width half-speed supplement cutting cylinders between the main web-members and on a higher level than the rotary first-folder and effective to cut off sheets in length equal to the width of one page plus margins; means for forwarding two main web-members, one on each side of the supplement cutting cylinders, to the main cutter and rotary folder; means for forwarding the supplement web to the supplement cutting cylinders; means

- for controlling the leading end of the supplement web on one supplement cutting cylinder; means for stripping the leading end of the supplement web from said cutter cylinder; means for controlling the leading end of the supplement web between two main web-members before making the tail end cuts of the respective supplement sheets; a single-width main cutter and a single-width 50 supplement sheet in each paper.
- 5 102. The combination of a plurality of plate-cylinders two pages in circumference and equipped with plates having columns parallel to the axes of the plate-cylinders and adapted to perfect both sides of a plurality of webs in width equal to the length of two pages plus margins; means for slitting the perfected webs to form a plurality 70 of main web-members and a supplement web-member; means for turning the web-members and disposing them in single-width alinement: two opposite single-width rotary 75 first-folders; two single-width main cutter cylinders equipped with cutting devices spaced apart a distance equal to the width of two pages plus margins; means for propelling the main web members, to the main cutters and rotary folders on each side of 80 the supplement cutting cylinders; a pair of full-speed single-width supplement cutting cylinders on a higher level than the rotary first-folders and equipped with cutting devices and sheet holding devices spaced apart 85 a distance equal to the width of one page plus margins and adapted to propel supplement sheets downwardly and alternately in different directions next to the inner side of the main webs into position for the main 90 webs to control the supplement sheets before cutting off the main sheets; means for propelling the supplement web member between the main web members to the supplement cutting cylinders and controlling the leading 95 end of the supplement web-member; means for forwarding first-folded sheets to the second folders; two second folders at right angles to the first-folders and adapted to make the second fold across the crease of the first fold; and two delivery devices 100 co-operating with the second-folders respectively.
100. The combination of full-speed main plate cylinders effective to print both sides of a full-speed main web a plurality of pages in width; half-speed plate cylinders 105 effective to print both sides of a single width supplement web; means for slitting the main web into single-width web-members and associating said web-members on the main cutter; one single-width, full-speed rotary first-folder; a single-width main cutter adapted to cut from main web members sheets in length equal to the width of two pages plus margins; a single-width half-speed supplement cutter on a higher level 110 than the rotary first-folder and adapted to cut supplement sheets in length equal to the width of one page plus margins; means for forwarding the supplement cuts downwardly between main web-members to the 115 main web to form two single-width web-members; means for associating both web-members on one main cutter; one single-width full-speed rotary first-folder; one single-width main cutter; two co-acting single-width half-speed supplement cutting cylinders on a higher level than the rotary first-folder and adapted to cut supplement sheets in length equal to the width of one page plus margins; means for forwarding the single-width main web-members on both sides of the supplement cutting cylinders to the main cutter and rotary first-folder; means for forwarding the supplement web to the supplement cutting cylinders; means for controlling the leading end of the supplement 120 125 130
101. The combination of printing means effective to print a full-speed main web two pages in width and a half-speed supplement web one page in width; means for slitting the main web to form two single-width web-members; means for associating both web-members on one main cutter; one single-width full-speed rotary first-folder; one single-width main cutter; two co-acting single-width half-speed supplement cutting cylinders on a higher level than the rotary first-folder and adapted to cut supplement sheets in length equal to the width of one page plus margins; means for forwarding the single-width main web-members on both sides of the supplement cutting cylinders to the main cutter and rotary first-folder; means for forwarding the supplement web to the supplement cutting cylinders; means for controlling the leading end of the supplement 130
102. The combination of a plurality of plate-cylinders two pages in circumference and equipped with plates having columns parallel to the axes of the plate-cylinders and adapted to perfect both sides of a plurality of webs in width equal to the length of two pages plus margins; means for slitting the perfected webs to form a plurality 70 of main web-members and a supplement web-member; means for turning the web-members and disposing them in single-width alinement: two opposite single-width rotary 75 first-folders; two single-width main cutter cylinders equipped with cutting devices spaced apart a distance equal to the width of two pages plus margins; means for propelling the main web members, to the main cutters and rotary folders on each side of 80 the supplement cutting cylinders; a pair of full-speed single-width supplement cutting cylinders on a higher level than the rotary first-folders and equipped with cutting devices and sheet holding devices spaced apart 85 a distance equal to the width of one page plus margins and adapted to propel supplement sheets downwardly and alternately in different directions next to the inner side of the main webs into position for the main 90 webs to control the supplement sheets before cutting off the main sheets; means for propelling the supplement web member between the main web members to the supplement cutting cylinders and controlling the leading 95 end of the supplement web-member; means for forwarding first-folded sheets to the second folders; two second folders at right angles to the first-folders and adapted to make the second fold across the crease of the first fold; and two delivery devices 100 co-operating with the second-folders respectively.
103. The combination of a plurality of full-speed plate-cylinders two pages in circumference and equipped with a single set of plates having columns parallel to the axes of the plate-cylinders and adapted to perfect both sides of a plurality of webs in width equal to the length of two pages plus margins; half-speed plate cylinders adapted to perfect both sides of a single width supplement web; means for slitting the main webs; means for turning the main web-members to dispose them in single-width alinement; one single-width rotary first folder; a single width main cutter having cutting means spaced apart a distance equal to the width of two pages plus margins; a pair of half-speed single-width sup-

- plement cutting cylinders adapted to cut supplement sheets in length equal to the width of one page plus margins; a second-folder at right angles to the rotary first-folder; means for forwarding the perfected main web-members to the main cutter and the rotary first folder with a web-member or web members, on each side of the supplement cutting cylinders; means for forwarding 5 the supplement web between the main web-members to the supplement cutting cylinders; means for taking and holding the leading end of the supplement web on one supplement cutting cylinder; means for 10 stripping the supplement web from said supplement cutting cylinder and propelling it downwardly between the main web-members before cutting off the supplement sheets; means for forwarding the first folded sheets 15 to the second-folder; and a second-folder adapted to make the second fold across the crease of the first fold; to produce one complete paper printed from a single set of plates for main pages and including a two 20 page supplement.
104. The combination of a plurality of full-speed main plate cylinders two pages in circumference and equipped with plates having columns parallel to the axes of the 25 plate cylinders and adapted to perfect both sides of a plurality of continuously moving webs in width equal to the length of two pages plus margins; half speed plate cylinders effective to perfect both sides of a 30 single-width supplement web; means for slitting the main webs to form web-members in width equal to the length of one page plus margins; means for turning the web members to dispose them in single-width 35 alinement; a single-width full-speed main cutter adapted to cut the main web-members into main sheets in length equal to the width of two pages plus margins; a single-width rotary first-folder adapted to fold the 40 main sheets centrally; a pair of single-width half-speed supplement cutting cylinders on a higher level than the rotary first-folder and adapted to cut the supplement web into sheets in length equal to the width 45 of one page plus margins; and a second-folder on a lower level than and at right angles to the rotary first-folder and adapted to make the second fold across the crease of the first fold.
- 55 105. In a multiple-deck apparatus the combination of printing means comprising full-speed plate cylinders in circumference equal to width of two pages plus margins, and equipped with plates having columns 60 parallel to the axes of the plate cylinders and adapted to print both sides of two main webs with a single set of plates, and half-speed plate cylinders in circumference equal to the width of two pages plus margins and 65 equipped with plates having columns par-
- allel to the axes of the plate cylinders and adapted to print both sides of a supplement web; means for forwarding the perfected main webs and the perfected supplement web in parallel single-width alinement 70 with the half speed supplement web between the main webs; a half speed single-width supplement cutter on a higher level than the means completing the first fold and adapted to cut the supplement web into sheets in 75 length equal to the width of one page plus margins; means for associating both main webs, one on each side of the supplement cutter, in position to be cut by one main cutter; a full-speed single-width main cutter 80 and a rotary folder adapted to cut the associated main webs into sheets in length equal to the width of two pages plus margins and fold said main sheets along the central margin between the pages; means for forwarding 85 the leading end of the supplement web downwardly in position to be guided between the main webs before cutting off the supplement sheet; sheet-holding means adapted to take and hold the leading ends of 90 the associated main webs and the leading end of the supplement sheet before cutting off the main sheets; and a second folder on a lower level than the rotary first folder and adapted to make the second fold of the 95 downwardly running first-folded sheets at right angles to the crease of the first fold including one two-page supplement sheet in each paper.
106. In a multiple-deck apparatus the combination of printing means comprising full-speed plate cylinders in circumference equal to the width of two pages plus margins, and equipped with plates having columns parallel to the axes of the plate cylinders and adapted to print both sides of two main webs, and half-speed plate cylinders in 100 circumference equal to the width of two pages plus margins and equipped with plates having columns parallel to the axes of the plate cylinders and adapted to print both sides of a supplement web; means for forwarding both perfected main webs in parallel single-width alinement to one main cutter; a half-speed single-width supplement cutter on a higher level than the means completing the first fold and adapted to cut the supplement web into sheets in length 105 equal to the width of one page plus margins; means for associating both main webs on one side of the supplement cutter in position to be cut by one main cutter, a full speed single-width main cutter and a rotary folder adapted to cut the associated 110 main webs into main sheets in length equal to the width of two pages plus margins and fold said main sheets along the central margin between the pages; means for forwarding the supplement web downwardly; sheet holding means adapted to take and hold the 115
- 120
- 125
- 130

leading ends of the associated main webs and the leading end of the supplement sheet before cutting off the main sheets; and a second folder and adapted to make the second fold of the downwardly running first folder sheets at right angles to the crease of the first fold, including one supplement sheet in each paper.

107. The combination of a plurality of full-speed, main plate cylinders, two pages in circumference, and equipped with plates having columns parallel to the axes of the plate cylinders, and adapted to perfect both sides of a plurality of continuously moving webs in width equal to the length of a plurality of pages plus margins; two half-speed plate cylinders, two pages in circumference, and having columns parallel to the axes of the plate cylinders and adapted to perfect both sides of a single-width half-speed supplement web; a single-width full-speed main cutter and a single-width full speed rotary folder adapted to cut off main sheets in length equal to the width of two pages plus margins and fold the main sheets including a two-page insert between main sheets; single-width half-speed supplement cutting cylinders adapted to cut the half-speed supplement web into sheets in length equal to the width of one page plus margins; second folder-rollers at right angles to and on a lower level than the rotary folder; means for forwarding the main web-members on both sides of the supplement cutting cylinders, to the main cutter and rotary folder; means for forwarding the half-speed supplement web, between the main web-members to the half-speed supplement cutting cylinders; and means for controlling the supplement sheets between the main web-members, before cutting off the main sheets.

108. In an apparatus of the class described, the combination of printing means adapted to perfect a full-speed web in width equal to the length of two pages plus margins; printing means adapted to perfect a single-width half-speed supplement web; means for slitting the main web to form an outside main web-member and an inside main web-member; means for turning the main web-members to dispose them in single-width alinement; a single width main cutter and a single width rotary folder in operative relation to the printing means and adapted to cut main sheets and fold them centrally; a single-width half-speed supplement cutter and carrier device in operative relation to said main cutter and rotary folder; means for forwarding said inside main web-member to said main cutter and rotary folder,—means for forwarding said outside main web-member, to the same main cutter and rotary folder; means for forwarding the half-speed supplement web, be-

tween the main web-members to the half-speed supplement cutter and carrier; means for controlling the leading end of the supplement sheets, between the main web-members, before cutting off the tail end of said supplement sheets; means for forwarding first-folded sheets to a second folder; and a second folder on a lower level than at right angles to the first-folder and adapted to make the second fold across the crease of the first fold.

109. In a multiple-deck apparatus the combination of printing means comprising full-speed plate cylinders in circumference equal to the width of two pages plus margins, and equipped with plates having columns parallel to the axes of the plate cylinders and adapted to print both sides of two main webs, and half speed plate cylinders in circumference equal to the width of two pages plus margins and equipped with plates having columns parallel to the axes of the plate cylinders and adapted to print both sides of a supplement web; means for forwarding the perfected main webs and the perfected supplement web in parallel single-width alinement with the half-speed supplement web between the main webs; a half speed single-width supplement cutter on a higher level than the means completing the first fold and adapted to cut the supplement web into sheets in length equal to the width of one page plus margins; means for associating both main webs, one on each side of the supplement cutter, in position to be cut by one main cutter; a full-speed single-width main cutter and a rotary folder adapted to cut the associated main webs into main sheets in length equal to the width of two pages plus margins and fold said main sheets along the central margin between the pages; means for forwarding the leading end of the supplement web downwardly in position to be guided between the main webs before cutting off the supplement sheet; sheet holding means adapted to take and hold the leading ends of the associated main webs before cutting off the main sheets and a second folder adapted to make the second fold of the downwardly running first folded sheets, at right angles to the crease of the first fold including one supplement sheet in each paper.

110. The combination of printing means adapted to perfect on a plurality of full speed webs the matter of main pages and supplement pages; means for slitting the webs to form main web-members and a supplement web-member means for turning the web-members to dispose them in single-width alinement; means for forwarding downwardly in parallel two perfected full-speed main web-members and a perfected half-speed supplement web-member; a single-width supplement cutter between the

- downwardly moving main web-members; a single-width main cutter and a rotary folder on a lower level than the supplement cutter; and a paster positioned to apply paste along 5 the central margin between the main pages on the inside of one main web-member, to stick the tail-end margin of the supplement sheet on the central margin between main pages on the inside of one main web-member.
- 10 111. The combination of printing means effective to perfect a full speed main web in width equal to the length of two pages plus margins; and a half-speed supplement web in width equal to the length of one page 15 plus margins; means for slitting the main web and disposing the web-members in single-width alinement; means for forwarding in parallel, two perfected full-speed main web-members and a perfected half-speed 20 supplement web between the main web-members; a single-width half-speed supplement cutter between the main web-members and adapted to cut sheets in length equal to the width of one page plus margins, with the 25 leading ends of said sheets between and controlled by the main web-members; a main cutter parallel to the supplement cutter and adapted to cut main sheets in length equal to the width of two pages plus margins; a carrier co-acting with said main cutter; controlling devices adapted to control the leading ends of both main web-members and the leading end of the supplement sheet between the main web-members; and means adapted 30 35 to fold the main sheets including a two-page supplement sheet between main sheets in each paper.
112. The combination of printing means comprising plate cylinders two pages in circumference equipped with plates having columns lengthwise of the plate cylinders and adapted to perfect a full-speed main web in width equal to the length of two pages plus margins and a single-width half-speed 40 supplement web; means for slitting the main web to form web-members; means for turning the main web-members; means for forwarding the main web members in parallel with the supplement web between the main 45 web-members; a full-speed main cutter and a full-speed rotary folder adapted to cut the associated main web-members into sheets in length equal to the width of two pages plus margins and fold the sheets centrally along 50 the margin between the main pages; a half-speed supplement cutter between the main web-members and positioned to cut the supplement web into sheets in length equal to the width of one page plus margins, with 55 the leading end of the supplement web between and controlled by the main web-members before cutting off each supplement sheet; and a second folder adapted to make 60 the second fold across the crease of the first fold, to produce at each revolution of the 65

plate cylinders, a complete second-folded paper printed by a single set of plates for main pages.

113. In a multiple-deck apparatus the combination of printing means comprising 70 full-speed plate cylinders in circumference equal to the width of two pages plus margins, and equipped with plates having columns parallel to the axes of the plate cylinders and adapted to print both sides of two 75 main webs, and half speed plate cylinders in circumference equal to the width of two pages plus margins and equipped with plates having columns parallel to the axes of the plate cylinders and adapted to print 80 both sides of a supplement web; means for forwarding the perfected main webs and a perfected supplement web in parallel single-width alinement; a half-speed single-width supplement cutter on a higher level than the main cutter and the rotary first folder and adapted to cut the supplement web into sheets in length equal to the width of one page plus margins; means for associating both main webs in position to be cut by one main cutter; a full-speed single-width main cutter and rotary folder adapted to cut the associated main webs into main sheets in length equal to the width of two pages plus margins and fold said main sheets along the 90 central margin between the pages; means for forwarding the leading end of the supplement web downwardly in position to be guided between the main webs before cutting off the supplement sheet; sheet holding means adapted to take and hold the leading ends of the associated main webs and the leading end of the supplement sheet before cutting off the main sheets; and a delivery device on a lower level than the rotary first folder and adapted to receive first-folded sheets running downwardly with their first-folded edges in the lead. 100

114. In a multiple-deck apparatus the combination of printing means comprising 110 full-speed plate cylinders in circumference equal to the width of two pages plus margins, and equipped with plates having columns parallel to the axes of the plate cylinders and adapted to print both sides of two main webs, and half speed plate cylinders in circumference equal to the width of two pages plus margins and equipped with plates having columns parallel to the axes of the plate cylinders and adapted to print both sides of a supplement web; means for forwarding the perfected main webs and the perfected supplement web in parallel single-width alinement with a half-speed supplement web between the main webs; a half-speed-single width supplement cutter on a higher level than the means completing the first fold and adapted to cut the supplement web into sheets in length equal to the width of one page plus margins; means for disposing 115 120 125 130

- he main webs, one on each side of the supplement cutter, and associating them in position to be cut by one main cutter; a full-speed single-width main cutter and rotary folder adapted to cut the associated main webs into main sheets in length equal to the width of two pages plus margins and fold said main sheets along the central margin between the pages; a paster between the main webs in position to apply paste on one main web along the central margin between main pages; means for forwarding the leading end of the supplement web downwardly in position to be guided between the main webs before cutting off the supplement sheet; sheet holding means adapted to take and hold the leading ends of the associated main webs and the leading end of the supplement sheet before cutting off the main sheets; and a second folder adapted to make the second fold of the downwardly running first-folded sheets, at right angle to the crease of the first fold, including one supplement sheet pasted in each paper; and a delivery device positioned to receive the second folded papers.
116. In a multiple-deck apparatus the combination of printing means comprising full-speed plate cylinders in circumference equal to the width of two pages plus margins, and equipped with plates having columns parallel to the axes of the plate cylinders and adapted to print both sides of two main webs, and half-speed plate-cylinders in circumference equal to the width of two pages plus margins and equipped with plates having columns parallel to the axes of the plate cylinders and adapted to print both sides of a supplement web; means for forwarding the perfected main webs and the perfected supplement web in parallel single-width alinement with the half-speed supplement web between the main webs; a half-speed single-width supplement cutter on a higher level than the means completing the first fold and adapted to cut the supplement web into sheets in length equal to the width of one page plus margins; means for disposing the main webs, one on each side of the supplement cutter, and associating them in position to be cut by one main cutter; a full-speed single-width main cutter and rotary folder adapted to cut the associated main webs into main sheets in length equal to the width of two pages plus margins and fold said main sheets along the central margin between the pages; a paster between the main webs in position to apply paste on one main web along the central margin between main pages; means for forwarding the leading end of the supplement web downwardly, guided between the main webs, in position for the leading end of the supplement sheet to stick on the paste applied along the margins between the pages on one main web; sheet-holding means adapted to take and hold the leading ends of the associated main webs before cutting off the main sheets; and a second folder adapted to make the second fold of the downwardly running first-folded sheets, at right angles to the crease of the first fold, including one supplement sheet pasted in each paper.
117. In a multiple-deck apparatus the combination of printing means comprising full-speed plate cylinders in circumference equal to the width of two pages plus margins, and equipped with plates having columns parallel to the axes of the plate cylinders and adapted to print both sides of two main webs, and half-speed plate cylinders in circumference equal to the width of two pages plus margins and equipped with plates having columns parallel to the axes of the plate cylinders and adapted to print both sides of a supplement web; means for forwarding the perfected main webs and the perfected supplement web in parallel single-width alinement with the half-speed supplement web between the main webs; a half-speed single-width supplement cutter on a higher level than the means completing the first fold and adapted to cut the supplement web into sheets in length equal to the width of one page plus margins; means for disposing the main webs, one on each side of the supplement cutter, and associating them in position to be cut by one main cutter; a full-speed single-width main cutter and rotary folder adapted to cut the associated main webs into main sheets in length equal to the width of two pages plus margins and fold said main sheets along the central margin between the pages; a paster between the main webs in position to apply paste on one main web along the central margin between main pages; means for forwarding the leading end of the supplement web downwardly, guided between the main webs, in position for the leading end of the supplement sheet to stick on the paste applied along the margins between the pages on one main web; sheet-holding means adapted to take and hold the leading ends of the associated main webs before cutting off the main sheets; and a second folder adapted to make the second fold of the downwardly running first-folded sheets, at right angles to the crease of the first fold, including one supplement sheet pasted in each paper.

- of the plate cylinders and adapted to print both sides of a supplement web; means for forwarding the perfected main webs and the perfected supplement web in parallel single-width alignment; a half speed single-width supplement cutter on a higher level than the means completing the first fold and adapted to cut the supplement web into sheets in length equal to the width of one page plus margins; means for associating both main webs in position to be cut by one main cutter; a full speed single-width main cutter and rotary folder adapted to cut the associated main webs into main sheets in length equal to the width of two pages plus margins and fold said main sheets along the central margin between the pages; a paster adapted to apply paste on one main web along the central margin between the pages;
- means for forwarding the supplement web downwardly in position for the tail end of the supplement sheet to stick on the pasted margin between main pages on the main web; and sheet holding means adapted to take and hold the leading ends of the associated main webs and the leading end of the supplement sheet before cutting off the main sheets.
118. The combination of single-width half-speed supplement cutting and carrying cylinders co-acting to cut a half-speed supplement web into sheets in length equal to the width of one page plus margins; sheet holding means effective to cause all the supplement cuts to run on one of said cylinders; strippers adapted to strip the cuts from the effective cylinder; a full speed single width, main cutter cylinder and a full speed single-width main carrier cylinder adjacent to and in line with the supplement cutting and carrying cylinders; means for forwarding a full-speed main web on one side of the supplement cutting and carrying cylinders to said main cutter and carrier cylinders, and forwarding another full-speed main web on the other side of the supplement cutting and carrying cylinders to the same main cutter and carrier cylinders, in position for the leading end of the downwardly running supplement web to be inserted between the main webs before cutting off the supplement sheet; and a full speed single width rotary folder adapted to fold the main sheets cut by the main cutter, including one supplement sheet in each paper.
119. The combination of single-width half-speed supplement cutting and carrying cylinders co-acting to cut a half-speed supplement web into sheets in length equal to the width of one page plus margins; sheet holding means effective to cause all the supplement cuts to run on one of said cylinders; strippers adapted to strip the cuts from the effective cylinder; a full-speed single-width, main cutter cylinder and a full-speed single-width main carrier cylinder adjacent to and in line with the supplement cutting and carrying cylinders; means for forwarding a full-speed main web on one side of the supplement cutting and carrying cylinders to said main cutter and carrier cylinders, and forwarding another full-speed main web on the other side of the supplement cutting and carrying cylinders to the same main cutter and carrier cylinders, in position for the leading end of the downwardly running supplement web to be inserted between the main webs before cutting off the supplement sheet; and a full speed single width rotary folder adapted to fold the main sheets cut by the main cutter, including one supplement sheet in each paper.
- width main carrier cylinder adjacent to and in line with the supplement cutting and carrying cylinders; means for forwarding a full-speed main web on one side of the supplement cutting and carrying cylinders to said main cutter and carrier cylinders, and forwarding another full speed main web on the other side of the supplement cutting and carrying cylinders to the same main cutter and carrier cylinders, in position for controlling the leading end of the supplement web between the main webs before cutting off the supplement sheet; and a full speed single width rotary folder adapted to fold the main sheets cut by the main cutter, including one supplement sheet in each paper, and a second folder adapted to make the second fold across the crease of the first fold.
120. A single-width half-speed supplement cutter adapted to cut a single-width supplement web into sheets in length equal to the width of one page plus margins; means for forwarding a half-speed supplement web to the supplement cutter; means for forwarding one single-width full-speed main web on one side of the supplement cutter to a full-speed main-cutter and forwarding another single-width full-speed main-web on the other side of the supplement cutter to the same main cutter; a paster adapted to apply paste along the central margin between the pages of the inner side of one main web running to the main cutter; a full-speed single-width main cutter and a full-speed single-width main carrier adapted to cut into sheets in length equal to the width of two pages plus margins, single-width main-webs running on both sides of the supplement cutter and carry said sheets; means for leading the supplement web in position to be controlled between the main webs before cutting off the supplement sheet and with the supplement pages in register with the main pages; sheet-holding means adapted to take and hold the leading ends of the associated main webs, before cutting off the main sheets; and a rotary folder adapted to fold the main sheets centrally including a supplement sheet pasted in each paper.
121. A single-width half-speed supplement cutter adapted to cut a single-width supplement web into sheets in length equal to the width of one page plus margins; means for forwarding a half-speed supplement web to the supplement cutter; means for forwarding one single-width full-speed main web on one side of the supplement cutter to a full-speed main-cutter and forwarding another single-width full-speed main-web on the other side of the supplement cutter to the same main cutter; a paster adapted to apply paste along the central margin between the pages of the inner side of one main web running to the main cutter; a full-speed single-width main cutter and a full-speed single-width main carrier cylinder adjacent to and in line with the supplement cutting and carrying cylinders; means for forwarding a full-speed main web on one side of the supplement cutting and carrying cylinders to said main cutter and carrier cylinders, and forwarding another full-speed main web on the other side of the supplement cutting and carrying cylinders to the same main cutter and carrier cylinders, in position for controlling the leading end of the supplement web between the main webs before cutting off the supplement sheet; and a full speed single width rotary folder adapted to fold the main sheets cut by the main cutter, including one supplement sheet in each paper.

- full-speed single-width main carrier adapted to cut into sheets in length equal to the width of two pages plus margins; single-width main webs running on both sides of the supplement cutter and carry said sheets; means for leading the supplement web in position to be between the main webs before cutting off the supplement sheet and with the supplement pages in register with the main pages; sheet-holding means adapted to take and hold the leading ends of the associated main webs, before cutting off the main sheets; a rotary folder adapted to fold the main sheets centrally including a supplement sheet pasted in each paper, and a second folder adapted to make the second fold across the crease of the first fold. 122. The combination of two single width half-speed supplement cutting and carrying cylinders co-acting to cut a single width half-speed supplement web into sheets in length equal to the width of one page plus margins; sheet holding devices adapted to take and hold sheets on said cylinders respectively; controlling devices effective to control said sheet holding devices to cause the sheets to run on either of said cylinders, strippers co-acting with said cylinders respectively; supplement sheet forwarding devices co-operating with said cylinders respectively; a full speed single width main cutter, a full speed single width main carrier and a full speed rotary folder co-operating with one of said supplement sheet forwarding devices; and an opposite full speed single width main cutter, main carrier and rotary folder co-operating with the other supplement-sheet forwarding device; one main cutter, main carrier and rotary folder being adapted to cut carry and fold main sheets including a supplement sheet running from one supplement cutting and carrying cylinder, and the other main cutter, main carrier and rotary folder being effective to cut carry and fold main sheets, including a supplement sheet running from the other supplement cutting and carrying cylinder. 123. In apparatus of the class described the combination of two co-acting single width cutter cylinders operable at full speed, or optionally, at half speed; two opposite single width rotary folders on a lower level than said cutter cylinders; and means effective to forward all the cuts to one rotary folder when said cutter cylinders are operating at half speed, and likewise effective to forward the cuts alternately to the folders when said cutter cylinders are operating at full speed. 124. The combination of a single width main cutter and single width rotary first-folder adapted to cut and fold centrally sheets in length equal to the width of two pages plus margins; means for forwarding two main webs to the main cutter; single-width half-speed supplement-cutting means located between the two main webs; means for forwarding a half-speed supplement web to the supplement cutting means; a paster device between the main webs; means for forwarding the supplement pages in registry with the main pages; second folder means on a lower level than and at right angles to the rotary first-folder; means for carrying the first-folded sheets downwardly to the second folder; and means for delivering the second-folded product at right angles to the rotary first-folder, including one two-page supplement sheet in each paper. 125. The combination of a single width main cutter, a main carrier and a single width rotary first-folder, adapted to carry webs and cut and fold centrally sheets in length equal to the width of two pages plus margins; means for forwarding two main webs to the main cutter; single width half-speed supplement cutting means between the two main webs; means for forwarding a half-speed supplement web to the supplement cutting means; a paster device between the main webs; means for forwarding the supplement pages in registry with the main pages; a second-folder on a lower level than and at right angles to the rotary first-folder and in such position that the leading pages carried on the main carrier will be folded on the inside of the second-folded papers; and means for delivering the second-folded product at right angles to the rotary first-folder including a one-leaf two page insert sheet in each paper. 126. In an apparatus for printing and folding papers, the combination of means for perfecting two single-width full-speed main webs and forwarding them to and associating them on one main carrier; means for perfecting and forwarding a half-speed single-width supplement web to a half-speed supplement cutter between the main webs; a half-speed single width supplement cutter adapted to cut the supplement web into two-page sheets; a single-width full-speed main cutter adapted to cut the associated main web into four-page main sheets; a single-width full-speed newspaper carrier equipped with means for taking and holding the leading ends of the associated main webs and also equipped with rotary creaser-means adapted to crease the associated sheets at each cut of the main cutter; and folder rollers adapted to complete the first fold of the creased sheets. 127. In an apparatus for printing and folding papers, the combination of means for perfecting two single-width full-speed main webs and forwarding them to and associating them on one main carrier; means for perfecting and forwarding a half-speed single-width supplement web to a half-speed

supplement cutter between the main webs; a half-speed single-width supplement cutter adapted to cut the supplement web into two-page sheets; a single-width full speed main cutter adapted to cut the associated main webs into four-page main sheets; a single width full speed newspaper carrier equipped with means for taking and holding the leading ends of the associated main webs and also equipped with rotary creaser-means adapted to crease the associated

sheets, at each cut of the main cutter; folder rollers adapted to complete the first fold of the creased sheets; and a second folder adapted to make the second fold.

15

In witness whereof I have hereunto signed my name at Springfield, Illinois, this 25th day of August, 1910.

JOHN A. BOYCE.
